UNITED STATES PATENT OFFICE.

WILLIAM C. MEYER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-SEWING MACHINE.

1,411,798.

Specification of Letters Patent. Patented Apr. 4, 1922.

Application filed May 6, 1916, Serial No. 95,893. Renewed June 17, 1920. Serial No. 389,774.

To all whom it may concern:

Be it known that I, WILLIAM C. MEYER, a citizen of the United States, residing at Beverly, in the county of Essex and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

This invention relates to shoe machines and more particularly to shoe sewing machines of the type provided with a curved hook needle and employed in sewing inseams of shoes. Certain features of the invention, however, may be embodied in other types of shoe sewing machines, and certain features may be embodied in other machines for inserting fastenings in the parts of shoes.

One object of the invention is to provide shoe sewing machines for sewing inseams of welted shoes with novel and improved devices for severing the welt at a suitable distance from the end of the inseam after the inseam is sewn, and for presenting the free end of the welt in proper relation to the shoe at the beginning of the sewing of the seam and holding it in position to be sewn until the welt is attached to the upper and insole by one or more stitches.

In the present embodiment of the invention the machine is provided with welt gripping devices for gripping and holding the welt, welt cutting devices for severing the welt adjacent the end of the inseam at the completion of the sewing operation, and a supplemental welt holder for holding the end of the welt in proper relation to the shoe during the first part of the seam formation. During the normal operation of the machine the welt gripping and welt cutting devices and the supplemental welt holder are all retained in an inactive condition. As the machine is stopped at the completion of a sewing operation, the welt gripping and welt cutting devices are automatically placed in an operable condition and are thrown into operation by the drawing forward of the welt through the welt guide as the shoe is removed from the machine. After a predetermined length of welt has been drawn through the welt guide, the welt gripping and welt cutting devices are advanced into

operative positions, the welt gripping devices grip the welt in advance of the needle, and the welt cutting devices sever the welt in advance of the welt gripping devices at a suitable distance from the end of the completed inseam. For the sake of simplicity in the construction and operation of the welt gripping and cutting devices, and in order to enable the welt to be held in proper position against the upper, close to the point of operation of the needle during the formation of the first stitch, the welt gripping devices are fixed in the direction of feed and hold the end of the welt only until the new seam is started, after which the supplementary holder is thrown into operation and holds the welt against the shoe until one stitch has been completed. As the machine is started at the beginning of the sewing operation upon a shoe, the welt gripping devices release the welt, preferably after the needle has punctured the work in the first cycle of operations, but before the needle retracts, and the welt cutting and gripping devices are then retracted to inoperative positions. As the welt cutting and gripping devices are retracted the supplementary welt holder is advanced into engagement with the welt at a point close to the point of operation of the needle, and holds the welt against the upper of the shoe. During the retracting movement of the needle, the welt is held on one side of the needle by the welt guide and on the other by the supplementary welt holder, and is thus prevented from being drawn away from the shoe. In order to draw the welt through the welt guide as the shoe is fed forward during the first stitch formation, and thus to obviate any drag or strain on the welt tending to draw the end of the welt away from the shoe at the point where the thread loop has been drawn through the work, the welt holder is advanced in the direction of feed with the shoe as the shoe is fed. After the initial feed has taken place and the needle is advanced into engagement with the work for the formation of the second stitch, the supplementary welt holder is retracted out of operative position and remains inactive during the remainder of the sewing operation.

Another object of the invention is to provide inseam shoe sewing machines with improved mechanism for advancing and re-

tracting a work rest such as the welt guide of a welt machine or the back gage of a turn machine and for locking the work rest in advanced position during each cycle of operations.

Other objects of the invention are to improve the construction and operation of various parts of shoe sewing machines with the view of rendering such machines more reliable and efficient in operation.

The features of the invention will be readily understood from the accompanying drawings illustrating a machine embodying the invention in its preferred form, and the following detailed description of the constructions therein shown.

In the drawings, Figure 1 is a view in side elevation of an inseam shoe sewing machine embodying the invention looking from the left side of the machine; Fig. 2 is a view in front elevation of the machine; Fig. 3 is a view in side elevation of the machine looking from the right; Fig. 4 is a view in side elevation of a portion of the machine illustrating particularly the welt guide mechanism and certain associated parts; Fig. 5 is a detail view in side elevation illustrating the tension devices; Fig. 6 is a sectional view taken substantially on the line 6—6 of Fig. 5; Fig. 7 is a detail sectional view taken substantially on the line 7—7 of Fig. 5; Fig. 8 is a plan view illustrating certain parts of the tension mechanism detached; Fig. 9 is a detail view, partly in elevation and partly in section, illustrating certain parts of the tension mechanism; Fig. 10 is a detail view illustrating certain parts of the tension mechanism; Fig. 11 is a detail view illustrating certain parts of the mechanism shown in Fig. 10; Fig. 12 is a detail view illustrating certain parts of the tension release mechanism; Fig. 13 is a view in side elevation illustrating particularly the welt gripping and cutting devices; Fig. 14 is a sectional view taken substantially on the line 14—14 of Fig. 13; Fig. 15 is a sectional view taken substantially on the line 15—15 of Fig. 23; Fig. 16 is a sectional view taken substantially on the line 16—16 of Fig. 15; Fig. 17 is a view in side elevation illustrating particularly the driving and stopping mechanisms; Fig. 18 is a plan view illustrating the driving and stopping mechanisms and certain associated parts; Fig. 19 is a sectional view taken substantially on the line 19—19 of Fig. 18; Fig. 20 is a sectional view taken substantially on the line 20—20 of Fig. 18; Fig. 21 is a sectional view taken substantially on the line 21—21 of Fig. 18; Fig. 22 is a view, partly in side elevation and partly in section, illustrating particularly the supplementary welt holder and its controlling mechanism and the thread gripping devices; Fig. 23 is a view partly in plan and partly

in horizontal section illustrating the welt gripping and cutting devices, the supplementary welt holder and its actuating mechanism, the welt guide mechanism and the welt measuring mechanism; Fig. 24 is a view in vertical section taken substantially on the line 24—24 of Fig. 23; Fig. 25 is a view in side elevation illustrating the mechanism for controlling the retracting movement of the welt gripping and cutting devices and the advancing and retracting movement of the supplementary welt holder; Fig. 26 is a view in rear elevation of the mechanism illustrated in Fig. 25; Fig. 27 is a view in side elevation illustrating the welt measuring mechanism; Fig. 28 is a view in plan of the mechanism illustrated in Fig. 27; Fig. 29 is a detail view in side elevation illustrating the connection between the welt measuring mechanism and the tension release mechanism; Fig. 30 is a detail view in side elevation illustrating particularly the thread gripping and cutting devices; Fig. 31 is a detail plan view illustrating the parts shown in Fig. 30, with the portions of the frame to which they are attached omitted for the sake of clearness; and Fig. 32 is a view in front elevation of the construction shown in Fig. 30.

The machine illustrated in the drawings is a welt shoe sewing machine the parts of which are constructed and arranged for sewing the welt and upper to the insole of a lasted shoe. The machine is provided with a curved hooked needle arranged to enter the between substance of the insole from the outer or marginal side, so that the chain of stitches is laid on the welt, and a curved awl arranged to enter the between substance of the insole on the channel side, a thread arm, a looper, a takeup, an auxiliary takeup, and a welt guide. These parts have the same general construction, arrangement and mode of operation as the corresponding parts of the machine illustrated and described in the patent granted to the present applicant, No. 1,059,380, dated April 22, 1913.

The machine is also provided with a tension governor by which the tension on the thread is automatically varied with any change in the speed of the machine, with locking mechanism for locking the tension wheel from rotation during the stitch setting stroke of the takeup, and with tension release mechanism for relieving the thread of tension upon stopping the machine. The tension mechanism has the same general construction and mode of operation as the tension mechanism disclosed in the patent granted to the present applicant, No. 1,180,936, dated November 16, 1915, except that there is no variation in the tension during a cycle of operations.

Referring to the drawings, and more particularly to Figs. 1, 2, 3 and 4, 2 indicates

the curved hook needle secured in the usual manner to a needle carrier 4 mounted to oscillate upon a hollow stud 6 (see Fig. 22). The needle carrier 4 is connected by means of a link 8 (see Figs. 3 and 4) to one arm of a bell crank lever 10, the other arm of which is connected by a link 12 to a lever 14 pivoted at 16 at the rear of the machine frame and operated by a cam groove in a cam disc on the main shaft 18 of the machine.

The needle guide 20 is of well known construction, and is secured to or formed integral with a short shaft 22 journaled within the hollow shaft upon which the needle carrier is mounted. The needle guide is actuated positively from a cam actuated lever 24 and a link 26 connecting the lower end of the lever and an arm 28 secured to the outer end of the shaft 22.

The awl 30 of the machine illustrated in the drawings is curved in the arc of a circle of somewhat smaller radius than that of the needle and is mounted to oscillate on an axis slightly below and to the rear of the axis of the needle. The awl is clamped to an awl carrier 32 which is pivotally mounted on a stud 34 projecting from a block mounted upon a laterally movable feed member or lever 36 by which lateral movements are imparted to the awl to feed the work. The awl carrier 32 is connected by means of a link 38 (Figs. 3 and 4) to one arm of a bell crank lever 40, the other arm of which is connected by means of a link 42 to a cam actuated lever 43. The link 38 is connected at its respective ends with the awl carrier and the bell crank lever 40 by universal joints, so as to allow the awl carrier to move in the direction of feed while the bell crank is fixed or held from movement in that direction.

The channel guide, indicated at 46, is constructed and arranged to engage the channel of a shoe sole in the usual manner, and has the usual mode of operation, that is, it moves with the awl during the feed, and also has a movement toward and from the shoe. The channel guide is carried by the feed member 36, the guide being secured to the block 50 which carries the stud upon which the awl is mounted.

The feeding member 36 is mounted so as to be capable of moving laterally to actuate the awl and channel guide to feed the work and to return these parts to their initial positions after the work is fed. To this end, the feeding member 36 is mounted to slide upon its pivot stud 48, which is secured at one end in the frame of the machine, the projecting portion of the stud being somewhat longer than the bearing portion of the feeding member which slides upon the stud to allow for the sliding movement of said member. The lateral movements are imparted to the feeding member by means of an

actuating lever 50 (see Figs. 2 and 3) pivoted at 52 on the frame of the machine, and having two parallel arms 54 and 56. The connection between the lever 50 and the feeding member 36 consists of a pin 58 clamped in a slot in the arm 54 of the lever, and extending into a groove in the projection 60 on the feeding member. By adjusting the pin in the slot in the arm 54, the feeding movements imparted to the feeding member 36 may be varied to give the desired length of stitch. The arm 56 of the lever 50 carries a cam roll 57 engaging in a cam groove in a cam disk mounted on the main shaft 18 whereby oscillating movements are imparted to the lever to reciprocate the feeding member 36 longitudinally of the stud 48. To impart a slight inward and outward movement to the channel guide, so as to cause it to release the work upon its return movement in the direction of feed, the feeding member 36 is extended upwardly and rearwardly beyond its pivot, and carries a cam roll 62 engaging a cam groove in a cam disc mounted on the main shaft 18 of the machine.

The thread arm of the machine is indicated at 64. This arm is secured to the lower end of a shaft 66 (see Figs. 1, 2, 3 and 4) mounted in the frame of the machine at a slight inclination to the vertical. To the upper end of the shaft is secured a laterally extending arm 68 which is connected by means of a link 70 to a cam actuated slide 72 mounted in guides in the frame, and carrying at its rear end a cam roll 74 engaging in a cam groove in a cam disc mounted on the main shaft.

The looper is indicated at 76, and consists of an arm clamped at its upper end to a block 105 or sleeve 78 mounted to slide laterally and to oscillate on a hollow stud 80 secured to the frame of the machine. Lateral sliding movements are imparted to the sleeve 78 by means of an arm 82 secured to the forward end of a horizontal rock shaft 84, and provided at its lower end with a roll 86 engaging in a vertical slot in the sleeve. This connection between the arm and the sleeve permits the sleeve to oscillate on the stud 80 without interfering with the connection between the arm and the sleeve. The rear end of the rock shaft 84 is provided with an arm 88 having a cam roll 90 at its upper end engaging a cam groove in a cam disc at-

tached to the main shaft 18. Oscillating movements are imparted to the sleeve 78 by means of a cam actuated slide 92, the rear end of which is provided with a cam roll 94 engaging a cam in a cam disc on the main shaft 18, and the forward end of which is pivotally connected with an arm 94 projecting upwardly from the sleeve 78. The pin 96 which connects the slide 92 with the arm 94 is of sufficient length to permit the

arm to slide on the pin as the sleeve 78 is moved laterally on the stud 80.

The welt guide indicated at 98 (see Figs. 3, 4, 22 and 23) comprises the usual parts 5 for supporting and guiding the welt. The guide is mounted on the forward end of an arm 100 pivoted at 102 upon the forward end of the welt guide slide 104. At its rear end the arm 100 is provided with a cam 106 engaging in a cam slot 108 in a plate 110 secured to the frame of the machine, the shape of the slot being such that an oscillating movement is imparted to the arm 100 as the slide 104 is advanced and retracted. This 15 oscillating movement of the arm 100 causes the portion of the welt guide in proximity to the needle to move in a path which practically coincides with the path of the needle so that the welt is always positioned with 20 relation to the needle, regardless of the thickness of the work being sewn. The slide 104 is advanced and retracted to move the welt guide toward and from the shoe, and is locked in advanced position against 25 rearward or forward movements during each cycle of operations. The welt guide is locked in forward or work-engaging position during a part of each cycle of operations, including the period during which the 30 needle is retracting from the work. The welt guide is retracted out of engagement with the shoe during the feeding of the shoe, and is thereafter moved forward yieldingly into engagement with the shoe. The locking 35 of the welt guide against retracting movement causes the welt guide to furnish a firm support for the work, particularly during the retracting movement of the needle. The locking of the welt guide against forward 40 movement prevents the welt guide from moving forward and displacing the shoe as the channel guide is moved to disengage its acting end from the bottom of the channel. The mechanism for actuating and locking 45 the slide, in the construction illustrated, comprises a spring 112, a cam actuated lever 114, three separate roll clutches, the rolls of which are carried in clutch boxes 116, 118 and 120, and are controlled by a clutch actuating block 122 pivotally mounted on the 50 lower end of the lever 114. The clutch boxes are all mounted upon the rod 104, and the rod is supported at its rear end by the clutch actuating block 122 in which the rod 55 is slidably mounted. The relative movement of the rod and the clutch actuating block is limited by means of a screw threaded pin 124 arranged axially of the pivotal connection between the clutch actuating block and 60 the lever 114 and projecting into a slot in the rod. The forward end of the rod 104 is pivotally supported at the upper end of an arm 126 pivotally mounted on a block 128 secured to the frame of the machine. To 65 form a yielding stop for the welt guide

slide when no work is in the machine, a spring-pressed plunger 130 is mounted in the block 128 and is arranged to be engaged by an adjustable abutment screw 132 mounted in the lower end of the arm 126. To 70 enable the position of the welt guide to be adjusted with relation to the path of the needle, the block 128 is mounted in the frame of the machine so as to be capable of vertical adjustment. The block is adjusted vertically by means of an adjusting screw 134 having a bearing in the projection 136 on the frame, and threaded at its upper end into the block. The block is held in adjusted position by a bolt 138. 80

The welt guide slide is advanced to bring the welt guide into engagement with the shoe by means of the spring 112 which has its outturned ends engaged respectively in a socket in the forward end of an adjustable screw 140 threaded into an arm of a bracket attached to the frame and in a socket in the rear end of the welt guide slide. 85

The mechanism for locking the welt guide slide in advanced position, and for retracting the slide, comprises the three roll clutches hereinbefore mentioned, which are controlled by the clutch actuating block 122. Two of these clutches are utilized to lock the welt guide slide when the welt 90 guide is in advanced position, one clutch acting to lock the slide from rearward movement, and the other to lock the slide from forward movement, and the third clutch is utilized to retract the slide. One of the slide 95 locking clutches comprises the clutch box 118 in which are mounted the clutch rolls 144 arranged to be engaged by the inclined surfaces of the blocks 146 mounted in the clutch actuating block 122. These rolls rest 100 against flat surfaces formed on the rod 104, and are forced against these surfaces to clutch the rod and lock the rod in its advanced position when the block 122 is moved forward, by the engagement of the blocks 110 146 with the rolls. The clutch box 118 is formed on a sleeve 148 mounted on the rod 104 for longitudinal movement on the rod. This slide locking clutch locks the slide 105 against rearward movement. The second slide locking clutch comprises the clutch box 116 and the clutch rolls 150 mounted in the clutch box and resting against flat surfaces 115 formed on the rod 104. In the construction 120 illustrated, the clutch box 116 is formed integral with the sleeve 148, so that it is moved longitudinally on the rod 104 with the sleeve and with the clutch box 118. When the sleeve 148 is moved forward, the rolls 150 are engaged by the inclined faces of blocks 125 151 mounted in the arms 152 formed on a bracket 153 adjustably secured to the frame of the machine. Through the engagement of the inclined faces of the blocks 151 with the clutch rolls 150, the rolls are forced against 130

the rod 104 to clutch the rod. The sleeve is normally held in retracted position by a leaf spring 154. The retracted position of the sleeve is determined by an abutment screw 155 threaded into the bracket 153 and having an eccentric inner end arranged to engage behind a shoulder on the sleeve. The retracted position of the sleeve may be adjusted by an adjustment of the abutment screw. The second slide locking clutch locks the slide against forward movement. The clutch actuating block 122 is moved forward to engage the blocks 146 with the clutch rolls 144 after the welt guide has advanced into contact with the shoe. When the blocks 146 have engaged the clutch rolls 144, the continued forward movement of the block 122 causes the sleeve 148 to move forward a short distance, thereby engaging the clutch rolls 150 with the inclined faces of the blocks 151 to force these rolls against the rod 104. The rod is thus locked securely in forward position against rearward or forward movement by the action of both the roll clutches. The forward movement of the clutch block 122 and the clutch rolls 144 imparts a slight positive forward movement to the welt guide while the welt guide is in contact with the shoe, which gives a final positive squeeze to the work just before the welt guide is locked.

The roll clutch for retracting the slide comprises the clutch rolls 156 mounted in the clutch box 120 carried by a sleeve 157 mounted on the rod 104, the rolls engaging flat surfaces formed on the rod. The rolls are forced against the flat surfaces on the rod to clutch the rod when the clutch actuating block 122 is moved rearwardly by means of blocks 158 mounted on the clutch actuating block, and having inclined faces arranged to engage the rolls. The sleeve 157 is moved forward with the clutch actuating block 122 by means of a coiled spring 159 connecting the clutch box with the block. The forward movement of the sleeve is limited by means of a yoke shaped arm 160 formed on a bracket attached to the frame, the arm embracing the sleeve and being arranged to engage a shoulder 161 on the rear end of the sleeve.

The takeup (see Fig. 3) comprises the thread truck 162 mounted upon one arm of a lever 164 pivoted at 166 on the frame. The rear end of this lever has a block and slot connection with the forward end of an arm 168 of a three-armed lever 170 pivoted at 172 on the frame. This lever is formed with a rearwardly extending arm 174 carrying a cam roll engaging a cam formed on a cam disk mounted on the cam shaft 18. The take-up has substantially the same mode of operation as the take-up of the machine disclosed in Patent No. 1,059,380 referred to above; that is, it exerts a stitch-setting strain

on the thread while the needle is in the work, and also acts to pull thread from the supply for the succeeding stitch.

The auxiliary takeup indicated at 176 is mounted on a lever 178 which is pivotally mounted concentrically with the main takeup lever 164. An arm 180 on the auxiliary takeup lever is arranged to engage a spring-pressed plunger 182 when the auxiliary takeup is raised. The auxiliary takeup has the same mode of operation as the auxiliary takeup of the machine described in Patent No. 1,059,380.

The tension devices of the machine illustrated (see Figs. 1, 2 and 3) comprise a tension disc 188 around which the thread passes on its way from the supply to the work. The disc is provided with peripheral projections extending alternately in opposite directions from the disc, and formed at an inclination to the radial lines of the disc to cause the thread to be drawn down to the base of the projections, and to enable the thread to free itself readily from the disc. To cause the thread to be drawn down into the passageway formed by the projections on the disc 188, an auxiliary tension wheel 190 is provided, this wheel being mounted at the rear of the machine, as shown in Fig. 3. The hub of the tension wheel 190 is engaged by a friction washer 192 (see Fig. 10) which is pressed against the hub of the tension wheel by means of a sleeve 194 surrounding the stud 196 on which the tension wheel is mounted, and acted upon by a coiled spring 198 interposed between the sleeve and a collar or nut on the stud. The thread passes from the wax pot 200 of any suitable construction upwardly around the tension wheel 190, through the thread tube 202 around the tension disc 188, under the auxiliary takeup 176, over the main takeup 162, and through the eye of the looper 76 to the work. The resistance exerted by the auxiliary tension wheel 190 to the forward movement of the thread causes the thread to engage the tension wheel 188 tightly as soon as any strain is exerted upon the thread between the tension wheel 188 and the work, so that the thread is at once prevented from slipping around the tension disc 188 and the stitches at the beginning of the seam are sewn under full tension strain.

The tension disc 188 is rigidly secured to a short hollow shaft 204 (see Figs. 5, 6 and 7) mounted to turn in a bearing 206 in the frame. To the opposite end of the shaft 204 is rigidly secured a brake drum 208. Arranged to bear on the periphery of the brake drum are two brake shoes 210 and 212 having linings of felt indicated at 214 contacting with the exterior surface of the drum. The lower brake shoe 212 is pivotally connected with the end of an arm 218 pivoted at 220 on the frame. The brake

shoes are pivotally connected by means of a pin or stud 222, and the shoes are held in proper relation to the drum by means of a spring 224 coiled about the stud and having its ends bearing respectively on the brake shoes, as shown in Fig. 5. The brake shoes are forced into engagement with the periphery of the brake drum by the downward pressure of a lever 226 pivoted at 228 and having a clutch connection with the upper brake shoe. This clutch connection comprises a rod 230 pivotally connected at 232 with one end of the upper brake shoe, and extending upwardly through an aperture in a block 234 mounted on trunnion pins 236 in an opening in the lever 226. A clutch roll 238 is mounted in the block 234 between a flat surface formed on the rod 230 and a relatively inclined surface formed in the block 234. A coiled spring 240 is mounted in the block below the roll, and acts to force the roll against the flat surface of the rod 230 to clutch the rod to the block 234. When downward pressure is exerted on the lever 226, the block 234 is clutched to the rod 230, and the pressure is transmitted through the rod to the brake shoes. The lever 226 is lifted to release the tension upon the reversal of the direction of rotation of the cam shaft as the machine is stopped, and in order to ensure the disengagement of the clutch roll 238 from clutching engagement with the rod 230 when this occurs, a rod 242 is adjustably mounted in the frame in a position such that its lower end will engage the clutch roll 238 when the lever 226 is lifted. The rod 242 is threaded into the frame, and is provided at its upper end with a milled disc 244 by which it may be turned to adjust its lower end. With this clutch connection between the lever 226 and the brake shoe 210, the pressure delivered from the lever 226 through the rod 230 to the brake shoes will be unchanged by variations in the position of the upper brake shoe, resulting from the wearing away of the brake shoe linings or from any other cause. The lever 226 is engaged by an abutment 246 carried by a slide 248 mounted to slide longitudinally in a lever 250 pivoted at 252. This slide is provided with rack teeth meshing with the teeth of a segment formed on a hand lever 254 (see Figs. 5 and 8) pivoted at 256 on the lever 250, the hand lever being provided with a spring-pressed pin 258 arranged to engage the teeth of a segment 260 to hold the lever in adjusted position. The lever 250 is pressed upon by a spring-pressed pin 262 having its lower end engaging the lever, and acted upon by a coiled spring 264 coiled about the pin and engaging at its respective ends a collar on the pin and the lower end of an abutment sleeve 266 mounted in the forwardly extending arm of a lever 268 through which sleeve the pin 262 passes. The lever 268 is pivoted at 270, and has its rear end acted upon by a governor mechanism which acts through the lever to vary the pressure of the pin 262 on the lever 250 as the speed of the machine varies. This governor mechanism (see Figs. 9 and 21) comprises weights 272 mounted on levers 274 pivoted at 276 on a rotary sleeve 278, the upper inturned ends of which levers are arranged to engage a collar or flange 75 formed on a slide 280 mounted to slide longitudinally on the upper end of a shaft 282, and having an upwardly projecting pin 284 formed thereon which engages the under side of the rear end of the lever 268. The slide 280 is engaged by a coiled spring interposed between a collar on the slide and an adjustable collar threaded upon the shaft 282. The shaft 282 is mounted to turn in suitable bearings in the frame of the machine, and carries at its lower end a beveled gear 286 meshing with a beveled gear 288 mounted on the cam shaft of the machine. The sleeve 278 is mounted on the shaft 282 and secured to rotate with the shaft by means 80 of a pin 290. During the operation of the machine the sleeve 278 is rapidly rotated through its connection with the cam shaft of the machine, and the weights 272 are swung outwardly from the axis of the sleeve, 85 causing the inturned ends of the levers 274 to depress the slide 280 to an extent varying with the speed of the machine. The variations in the positions of the slide 280 cause variations in the pressure with which the pin 262 engages the lever 250, and this results in variations in the tension applied to the thread, the tension on the thread increasing as the speed of the machine decreases, and decreasing as the speed of the machine 90 increases.

The means for locking the tension disc from rotation when the takeup reaches the limit of its loop-drawing stroke, so as to prevent overthrow of the tension at the end 100 of the pulling-off operation, in the construction illustrated, comprises a brake band 292 (see Fig. 5) surrounding the brake drum 208. One end of the brake band is pivoted at 294 to the frame of the machine, and the other end is formed with a socket 296 in which engages the lower end of a rod 298. This rod passes at its upper end through a sleeve 300 (see Fig. 1) mounted in a block pivoted to the forward end of an arm 304. A spring 306 surrounds the rod and is interposed between a collar on the rod and the lower end of the sleeve 300. With this construction the downward swinging movement 110 of the arm 304 will compress the spring 115 and actuate the rod 300 to bring the brake band into locking engagement with the brake drum. The movement of the rod 298 in the sleeve 300 under the action of the spring is limited by the engagement of the 120

125

130

stop nut 308 threaded on the upper end of the rod with the upper end of the sleeve 300. Upon the return movement of the arm 304 from tension locking position the movement 5 of the sleeve after it engages the stop nut lifts the rod from engagement with the lower end of the socket in the brake band, allowing the brake band to free itself from the brake drum. The arm 304 is fast upon 10 a rock shaft 312 upon which is mounted a second arm 314 arranged to be engaged by the arms 316 of the takeup actuating cam lever 170.

To relieve the thread of tension when the 15 machine is stopped, the machine illustrated is provided with a tension release mechanism which, when the direction of rotation of the cam shaft is reversed, releases the brake shoes 210 and 212 from braking engagement with the brake drum 208, and also moves the sleeve 194 to release the pressure of the friction washer 192 on the hub of the tension wheel 190. The tension release mechanism comprises a swinging arm 310 20 (see Figs. 1 and 12) such as is ordinarily employed in tension release mechanisms adapted to be operated by a reversal in the direction of rotation of the cam shaft. This arm is pivotally connected to the arm 318 25 of a lever 320 pivoted at 322 on the machine frame. This lever is provided with a second arm 324 (see Fig. 5) having a socket in which engages the lower end of a rod 326 which has its upper end engaged in a socket 30 in the rear end of the lever 226. An adjustable abutment screw 328 is threaded into the arm 324 to engage the lower end of the rod. The lever 320 is provided with a third arm 330 (see Figs. 1 and 5) connected by 40 a link 332 with an arm 334 fixed to one end of the rock shaft 336. Fixed to the opposite end of this rock shaft (see Figs. 2 and 3) is a bell crank lever 338, through the upper arm of which passes a rod 340, the 45 rod having a collar or head 342 at its lower end which engages the upper arm of the bell crank. This rod passes at its upper end through the horizontal arm of a second bell crank 344 (see Fig. 10) pivoted at 346 on 50 the frame, and a stop nut 348 is threaded on the rod to engage the upper side of the arm. The forked upper end of the upper arm of the latter bell crank embraces the sleeve 194 and carries threaded pins 350 engaging in grooves formed in the sleeve. When the arm 318 of the lever 320 is swung 55 forwardly by the movement of the arm or link 310 upon the reversal of the direction of rotation of the cam shaft, the lever 226, through the engagement of the rod 326 therewith, is lifted to relieve the pressure of the brake shoes on the brake drum. At the same time, through the link 332, the arm 334, the rock shaft 336, the bell crank 338, 60 and the rod 340, the bell crank 344 is actu-

ated to move the sleeve 194 outwardly from the hub of the tension wheel 190, and thus relieve the pressure of the washer 192 on the hub of the tension wheel.

The present machine is also provided with 70 mechanism for drawing the welt guide back of its normally retracted position simultaneously with the release of the tension upon stopping the machine. The arm 126 which supports the forward end of the welt 75 guide slide is fixed to a shaft 352 (see Figs. 1, 2 and 3) mounted in the block 128. An arm 354 is formed on said shaft, and carries an adjustable abutment screw 356 arranged to be engaged by an arm 358 fixed 80 on the rock shaft 336. This latter arm is swung downwardly upon the reversal of the direction of rotation of the cam shaft, and through its engagement with the abutment screw 356, actuates the arm 354, the shaft 85 352 and the arm 126 to throw back the welt guide to the rear of its normal retracted position, so that the shoe may be readily removed from the machine, and another shoe readily placed in operating position. 90

During the sewing operation the machine is driven through a belt pulley 362 (see Fig. 17) secured to the end of the cam shaft and connected by a driving belt 364 with a pulley 366 mounted on a shaft 368 in 95 the base of the machine. The pulley 366 is connected through the beveled gears 370 with a sleeve 372 mounted on a driving shaft 374 and carrying one member 376 of the main driving clutch. The driving shaft 100 374 carries the other member 378 of the clutch, and also carries the driving pulley 380 through which motion is imparted to the driving shaft. The engagement of the members of the driving clutch is controlled 105 through a treadle 382 connected with the clutch operating wedge 384. When the treadle is depressed, the members of the driving clutch are forced into engagement, and the machine is driven at a speed dependent upon the pressure which the operator applies to the treadle. When the treadle is released the clutch members are 110 disengaged thereby, disconnecting the cam shaft from the driving shaft. 115

The upward movement of the treadle when it is released also throws into operation mechanism which reverses the cycle of operations of the stitch forming mechanism to cast off the thread from the needle, and 120 which brings the machine to rest with the parts in proper position for the removal of the shoe. This mechanism in the construction shown comprises a friction clutch which is normally disengaged, but which is engaged upon the release of the treadle. The driving member of the clutch rotates in a direction reverse to the direction of rotation of the cam shaft of the machine, and when the clutch is engaged, the driving 125 130

member first acts on the driven member of the clutch as a brake to arrest the rotation thereof and of the cam shaft to which it is fixed, and then, as a driver to drive the driven member and the cam shaft in a reverse direction to stopping position. The driving member 386 of the slow speed clutch (see Figs. 18, 19, 20 and 21) is loosely mounted on the cam shaft of the machine and is formed on its periphery with spiral teeth 388 meshing with the teeth of a spiral driving pinion 390 secured to a shaft 392. The shaft 392 is continuously driven from the driving pulley by means of a belt 394 passing over a pulley 396 fixed to the outer end of the shaft, and over a pulley 398 formed on the driving pulley 380. The driven member of the slow speed clutch, indicated at 400, is carried by a sleeve 402 which is loosely mounted on the hub of the driving member 386 of the clutch, and is free to slide axially thereof to engage and disengage the clutch. The clutch members are constructed to secure a particularly efficient clutching action when they are engaged, and to obviate all objectionable sticking of the clutch when the driven member is shifted to disengage the clutch.

The driven clutch member comprises a rim 404 having an exterior cone-shaped face and a split clutch ring 406 keyed to the rim and having an interior cone-shaped face fitting against the exterior face of the rim. The clutch ring 406 is connected to rotate with the rim by a key 408 mounted in the rim and projecting outwardly therefrom between the ends of the ring. This key is preferably arranged obliquely to the axis of the clutch, so that the clutch ring will be given a slight rotary movement when the rim is moved axially with relation to the ring. The clutch ring is formed with an exterior clutch face arranged to engage the interior clutch face of the driving member 386 of the slow speed clutch. The elements of the engaging faces of the rim 404 and the clutch ring have a greater inclination to the axis of the clutch than the elements of the outer or clutch face of the ring and the clutch face of the driving clutch member which it engages. The clutch ring is held in place on the rim 404 with a shoulder 410 on the ring engaged with a flange 412 on the rim by a retaining ring 414 having a flange 416 engaging in a groove in the clutch ring. The retaining ring 414 is supported by screws 418 passing through perforations in the rim 404 and threaded into the retaining ring, and the ring 414 is pressed against the clutch ring to hold the clutch ring in position on the rim 404 by coiled springs 420 seated in recesses in the rim and acting against the heads of the screws. The groove in the clutch ring in which the flange 416 engages is somewhat wider than the flange to permit the clutch

ring to contract and expand relative to the retaining ring. This construction enables the driving and driven members of the clutch to be formed with their elements inclined at a much smaller angle to the axis of the clutch than is usual in clutches of this character without causing any objectionable sticking of the clutch when it is disengaged. With this construction the clutch ring is normally held in the position shown in Fig. 21, with its shoulder 410 in engagement with the flange 412 on the rim 404 by the action of the springs 420, the inner cone face of the ring then resting against the outer or cone face of the rim. The angle of inclination of the elements of the clutch faces of the clutch ring and the driving member is such that an efficient driving engagement between these parts is assured. When the sleeve 402 is shifted longitudinally of the cam shaft to disengage the clutch, if there is any undue friction between the clutch surfaces of the clutch ring and the driving member of the clutch tending to resist this movement, the rim 404 will move axially to a slight extent independently of the ring to disengage the outer face of the rim from the interior cone face of the ring, this movement of the rim independently of the ring being permitted by the yielding of the springs 420. When the outer face of the rim is disengaged from the ring, the ring is permitted to contract slightly so as to relieve the friction between its clutch face and the clutch face of the driving member of the clutch and thus allow the clutch to be readily disengaged. After the clutch is disengaged, the ring is restored to its normal position on the rim 404 by the action of the springs 420.

While the sleeve 402 is free to slide on the hub of the driving clutch member longitudinally of the cam shaft, it is connected to rotate with the shaft by means of a lug 422 projecting from the pulley 362 and engaging between lugs 424 formed on the sleeve. The sleeve is normally held in position on the hub of the driving clutch member with the members of the clutch disengaged by a spring 426 seated in a recess or bore in the pulley 362 and acting against the head of a pin 428 passing through the spring and through an opening in the pulley and threaded into the sleeve 402.

When the clutch members 386 and 400 are engaged, they first act on the cam shaft as a friction brake to absorb the energy due to momentum, and after the forward movement of the cam shaft has ceased, the clutch acts to turn the shaft in a reverse direction at a comparatively slow speed until the clutch is disengaged, when the cam shaft is brought to rest with the needle and other parts of the stitch forming mechanism in the proper position for the removal of the shoe. The mechanism for engaging and dis-

engaging the clutch at the proper times in the rotation of the cam shaft comprises a cam groove 430 formed in the sleeve 402 and engaged by a roll 432 on one arm of a bell crank lever 434. The other arm of the bell crank lever is provided with a hole 436 adapted to receive a locking pin 438 which is normally held out of engagement with the lever so that, during the normal running of the machine, the lever is oscillated idly by the cam. The locking pin is mounted on one end of a slide 440 which is held in normal position by a spring 442. The spring surrounds a bolt or rod 444 extending from the forward end of the slide, and is interposed between a shoulder on the slide and the inner end of an adjustable screw threaded sleeve 446 surrounding the rod and threaded into the frame of the machine. The movement of the slide under the action of the spring 442 is limited by the engagement of a stop nut 448 threaded on the forward end of the rod 444 with the forward face of a bracket 450 on the frame through which the rod passes. By adjusting the sleeve 446 the tension of the spring may be varied, and by adjusting the nut 448 the slide may be adjusted to bring the locking pin into proper position to register with the hole in the end of the lever 434. The locking pin is forced in a direction to engage its upper end in the opening in the arm of the bell crank lever by a spring 452, and the lower end of the pin is connected with the treadle 382 so that the pin is held down out of engagement with the bell crank lever as long as the treadle is depressed and the main driving clutch is engaged to drive the cam shaft of the machine. A latch 454 is also connected with the lower end of the locking pin, and is arranged to engage a shoulder 456 on the slide 440 and hold the locking pin in lowered position during the movements of the treadle imparted by the operator in varying the speed of the machine at different points in the sewing operation. In the construction shown, the latch 454 is loosely mounted on a shaft 458 carried in a block 460 secured to the lower end of the locking pin. The hub of the latch is formed with spaced lugs 462 fitting between corresponding lugs 464 on the hub of an arm 466 pivoted on the shaft 458. As will be noted from an inspection of Fig. 19, the lugs 462 on the hub of the latch are somewhat narrower than the spaces between the lugs 464 on the hub of the arm 466, so that there is a certain amount of lost motion between the arm and the latch when the arm is turned about the shaft. The arm 466 is connected by a treadle rod 468 with the treadle 382. When the treadle is depressed the arm 466 turns on the shaft 458, and through the engagement of the lugs 464 on the arm with the lugs 462 on the hub of the latch 454, the latch is turned until it brings up against the slide 440 and then, during the continued downward movement of the treadle, the locking pin is drawn down against the tension of its spring. 70 During the downward movement of the locking pin the latch 454 is depressed until its upper end is carried beneath the shoulder 456 on the slide. During the variations in the positions of the treadle occurring during the sewing operation for the purpose of varying the speed of the machine, the engagement of the latch with the shoulder 456 maintains the locking pin out of engagement with the hole in the arm of the bell crank 434. When the treadle is released, the latch 454 prevents the upward movement of the locking pin until the lugs 464 on the hub of the arm 466 strike the lugs 462 on the hub of the latch and swing 80 the latch outward, thus disengaging it from the shoulder 456. When this takes place, the spring 452 forces the locking pin upward against the under side of the bell crank lever, and when the hole in the lever registers with the pin, the pin snaps upward into the hole, thus connecting the lever with the slide 440. 85

The cam 430 is so timed that the hole in the end of the arm of the bell crank lever is brought into position to register with the locking pin at the proper time in the cycle of operations of the stitch forming mechanism. When the pin is engaged with the hole in the arm of the bell crank lever, the 90 lever is held from movement about its pivot and the cam 430, acting on the roll 432 carried by the lever, shifts the sleeve 402 to bring the members of the slow speed clutch into engagement. When the lever and slide 100 95 are locked together by the locking pin, the movement of the lever is resisted by the spring 442, and the force with which the members of the friction clutch are pressed together will depend upon the compression 105 of the spring. This may be adjusted to secure the desired braking effect between the members of the friction clutch, so that the forward rotation of the cam shaft will be arrested within the desired part of a revolution. 110 In the construction shown, the parts are so timed and controlled that the locking pin is engaged with the lever, and the friction clutch engaged, while the needle is retracted, and just before it begins its advance movement, and the forward rotation of the cam shaft is arrested after the needle has advanced and enters the work. The clutch then acts to turn the cam shaft in a reverse direction at slow speed until the 115 shaft arrives at the point where the cam 430 acted to engage the members of the clutch, when the reversely moving cam acts again to disengage the clutch members. The cam shaft is, therefore, brought to rest with 120 125 130

the needle in its retracted position, and the other parts of the stitch forming mechanism in such position that they do not interfere with the removal of the shoe. The reversal 5 of the cycle of operations after the needle has penetrated the work causes the needle to be retracted without a loop of thread in its hook, and consequently the last loop drawn out by the needle is cast off so that 10 the needle is automatically freed from the thread.

When the slow speed reversing clutch is disengaged the reverse movement of the cam shaft is arrested by a friction brake 15 so as to prevent any accidental over-running of the shaft. In the construction shown, this friction brake comprises a pair of brake shoes 470 and 472 (see Fig. 20) mounted within the laterally projecting flange 474 20 formed on the pulley 362, the brake shoes being arranged to engage the interior surface of the flange. The lower ends of the brake shoes are connected by a toggle comprising pivotally connected links 476 and 478, which 25 toggle is operated to engage the brake shoes with the brake flange 474 and to disengage the brake shoes therefrom at the proper times. At their upper ends, the brake shoes are guided upon pins 480 projecting laterally 30 from a block 482 (see Fig. 21). The upper end faces of the brake shoes are held by a spring 484 against an eccentric head 486 formed on a pin or rod 488 passing through an opening in the block 482 and 35 through an opening in the head of a draw bolt 490 which engages in a recess in the block. The draw bolt is mounted in a slot in the frame of the machine and a nut 492 is threaded on the upper end of the bolt. 40 The draw bolt acts to secure the block 482 to the frame and to clamp the pin 488 in adjusted position. By loosening the nut 492 the pin 488 is unclamped so that it may be turned to adjust the brake shoes with 45 relation to the brake flange 474. Upon the reversal in the direction of rotation of the cam shaft the brake shoes are engaged with the brake flange to arrest the reverse rotation of the cam shaft after the disengagement 50 of the driven member of the slow speed reversing clutch from the driving member. The brake shoes are disengaged from the brake flange as the treadle is depressed by the operator to start the machine 55 so that the cam shaft is freed from the action of the brake when the shaft is connected with the main driving mechanism and the machine may be started without undue resistance. The mechanism for actuating the 60 toggle to engage the brake shoes with the brake flange comprises a link 494 pivotally connected at its upper end with the central joint 496 of the toggle, a lever 498, a link 500 connecting the rear end of the lever with the 65 lower end of the link 494, a rod 502 pivotally

connected to the forward end of the lever and passing at its upper end through an opening in an arm 504 of the lever 320, and a spring 506 interposed between the arm 504 and a collar 508 held in position by a nut threaded on 70 the rod. The movement of the rod through the opening in the arm 504 is limited by a collar 510 mounted on the rod to engage the under side of the arm. The mechanism for operating the toggle to disengage the brake 75 shoes from the brake flange 474 upon the depression of the treadle comprises a lever 512, a link 514 connecting the lower arm of the lever with a pivotal connection 516 between the links 494 and 500 and 80 a link 518 connecting the upper arm of the lever 512 with the collar 520 clamped on the treadle rod 468. As the rotation of the cam shaft is reversed upon stopping the machine the movement of the lever 320, 85 through the rod 502, actuates the lever 498 to depress the link 500 and the link 494 connected therewith. The downward movement of the link 494 tends to straighten the toggle consisting of the links 476 and 478 and 90 the brake shoes 470 and 472 are engaged with the brake flange 474 by the movement of the toggle. The frictional engagement between the brake shoes and the brake flange arrests the rotation of the cam shaft after 95 the slow speed reversing clutch is disengaged. As the treadle is depressed to start the machine through the connection between the lever 512 and the treadle rod, the lever is 100 swung in a direction to throw the link 514 toward the rear of the machine. This movement of the link 514 swings the link 500 about its pivotal connections with the lever 498 and elevates the link 494 to diminish the angle between the toggle links 476 and 478 105 and thereby release the brake shoes from the brake flange. When the main driving clutch is engaged to start the machine the cam shaft is entirely freed from the resistance 110 of the brake.

After the sewing operation has been completed and the machine has been brought to rest with the needle free from the thread and the stitch forming devices in position for the removal of the shoe, the welt is 115 severed and the severed end of the welt held in position for attachment to the shoe at the beginning of the next sewing operation. The devices for severing and holding the welt in the construction shown (see Figs. 120 13, 14, 15 and 16), comprise the welt gripping jaws 522, 524 and the welt severing knife 526 which are held in retracted position during the sewing of the shoe and are advanced to sever and hold the welt after 125 the sewing operation has been completed and the machine brought to rest. The welt gripping jaws are respectively formed on levers 528 and 530 carried upon the front end of a slide bar 532 mounted to slide in guides 130

in a fixed bracket 534 on the frame and held in place in the guides by plates 536. The levers 528 and 530 carrying the welt gripping jaws are respectively pivotally supported on the slide bar 532 by means of pivot pins 538 and 540 and are normally held in open position by a spring 542. The gripper bar 532 is grooved to form a guide for the knife bar 544 to the forward end of which the knife 526 is secured. The knife bar 544 carries rolls 546 mounted upon a pin 548 threaded into an opening in a boss 550 formed on the knife bar which projects through a longitudinal slot 552 in the gripper bar. These rolls are arranged to engage cam faces 554 and 556 formed respectively on the rear ends of the levers 528 and 530, to actuate the levers to close the welt gripping jaws. The cam face 556 on the lever 530 is formed on an irregularly shaped plate 558 having a thin spring arm 560 and attached to the body of the lever by a screw 562. To reinforce the action of the spring arm a leaf spring 564 is secured to the body of the lever 25 and bears on the spring arm as shown in Fig. 13. This construction enables the lower welt gripping jaw to yield readily to accommodate itself to different thicknesses of welt. The gripper bar 532 is advanced and retracted by the movements of the knife bar 544. The lever 528 on which the upper gripping jaw is mounted is formed with a lateral projection 566 which engages in a recess 568 in the upper plate 536 when the gripper bar 35 is in advanced position as shown in the drawings. When the knife bar and the gripper bar are both in retracted position the upper face of the lateral projection 566 lies below the lower face of the upper plate 536 at the rear of the recess 568 and the rolls 546 lie behind the cam faces 554 and 556 on the jaw-carrying levers, the gripping jaws then being held in open positions by the spring 542. During the first part of the advancing movement of the knife bar the gripper bar is advanced with the knife bar through the engagement of one or more of the rolls 546 with the cam face 554. As the rolls engage the cam face 554 the movement 50 of the lever 528 on its pivot is limited by the engagement of the upper face of the projection 566 with the lower face of the upper plate 536 and the gripper bar is advanced with the knife bar. The forward movement 55 of the gripper bar is limited by the engagement of a shoulder 574 formed on the gripper bar with the rear end of the lower plate 536. After the gripper bar reaches its advanced position and its forward movement 60 is arrested, the forward movement of the knife bar continues, and through the engagement of the rolls 546 with the cam faces 554 and 556 on the rear ends of the levers 528 and 530, the levers are actuated to close the 65 welt gripping jaws, the projection 566 be-

ing engaged in the recess 568 during the jaw closing movement of the levers. After the welt gripping jaws have closed on the welt the continued forward movement of the knife bar advances the knife into engagement with the welt and the welt is severed by the knife close to the gripping jaws. The welt gripping jaws are held in gripping engagement with the welt until the knife bar is retracted through the engagement of the 70 rolls 546 with the inner faces 576 and 578 formed on the rear ends of the levers 528 and 530. During the first part of the reTRACTING movement of the knife bar the gripper bar 532 is prevented from retracting 75 with the knife bar by the engagement of the rear face 570 of the projection 566 with the rear face of the recess 568 until the rolls 546 clear the cam face on the rear end of the lever 528. The levers 528 and 530 are then 80 actuated by the spring 542 to open the welt gripping jaws to release the welt and the projection 566 is disengaged from the recess 568. This permits the gripper bar to retract and the gripper bar is then retracted with 85 the knife bar through the engagement of the boss 550 with the rear end of the slot 552 in the gripper bar.

The knife bar is advanced and retracted by the movements of a gear segment 580 90 pivoted on the frame and engaging a rack formed on the knife bar. The gear segment 580 is acted upon by a heavy coil spring 584 attached at its lower end to the gear segment and at its upper end to the 100 frame, which spring operates through the segment to hold the knife bar and gripper bar normally in retracted position. The gear segment is actuated to advance the knife bar through a link 586 having a slot 588 at its 105 lower end in which engages a roll 590 mounted on the gear segment. The upper end of the link is pivotally connected to one arm of a bell crank lever 592 pivoted at 594 on the frame and having its other arm connected with an eccentric strap 596 surrounding an intermittently rotating eccentric 598. The eccentric (see Figs. 19, 20 and 21) is mounted on a sleeve 600 journaled on a bushing 602 which forms a bearing for the cam 110 shaft. The eccentric is intermittently rotated by means of a roll clutch adapted to connect intermittently the eccentric carrying sleeve with the driving clutch member 386. In the construction shown the roll clutch 115 comprises clutch rolls 604 interposed between flat surfaces 606 on the eccentric carrying sleeve and an opposed cylindrical surface 608 formed on the driving clutch member 386. The rolls are controlled by means 120 of a roll carrying ring 610 provided with projecting lugs 612 between which the rolls are placed. A spring 614 connects the eccentric carrying sleeve and the roll carrying ring and tends to turn the ring in a direc- 125 130

tion to wedge the rolls between the flat surfaces on the eccentric carrying sleeve and the opposed surface of the driving clutch member to engage the clutch. Spring-pressed latching pins 618 suitably mounted in a frame are provided to hold the sleeve against backward rotation when the clutch is disengaged, the acting ends of these pins being arranged to engage in a notch 619 formed in the sleeve. The roll carrying ring is held in position to hold the clutch rolls out of action by one or the other of two latches 620 and 622, which are adapted to engage a stop dog 624 carried by the ring. During the operation of the machine in sewing a seam the dog 624 is in engagement with the latch 620 which is arranged a short distance in advance of the latch 622. When the parts are in this condition the eccentric, the lever 592, and the link 586 are in position to permit the spring 584 acting on the gear segment 580 to hold the knife bar 544 and the gripper bar 532 in retracted positions. When the knife bar and the gripper bar are retracted the welt gripping jaws and the welt cutting knife are in positions such that they do not interfere with the manipulation of the shoe during the sewing operation.

To prevent undue shock or vibration when the dog 624 is engaged by either of the latches 620 and 622, the dog is yieldingly mounted in the roll carrying ring. The dog is formed with a substantially cylindrical bearing portion 626 mounted to turn in a cylindrical bearing in the roll carrying ring, the body of the dog projecting outwardly through a slot in the ring in a position to be engaged by the latches as shown in Figs. 19 and 20. The dog is engaged upon its rear side by a coiled spring 628 mounted in the roll carrying ring, which serves to cushion the engagement of the dog with the latches.

When the sewing operation has been completed and the welt is to be severed, the latch 620 is lifted to release the roll carrying ring 610. This throws the clutch into action and the eccentric carrying sleeve is rotated through nearly a complete revolution or until the dog 624 is engaged by the latch 622 to disengage the clutch. During substantially the first half revolution of the eccentric the gear segment 580 is rocked to advance the knife bar and the gripper bar. The knife bar and the gripper bar move forward together until the welt gripping jaws have passed on opposite sides of the welt, and a guard 629 mounted on the lever 530 has engaged the edge of the welt when the forward movement of the gripper bar is arrested by the engagement of the shoulder 574 on the gripper bar with the rear end of the lower plate 536. The knife bar then advances independently of the gripper bar,

and through the engagement of the rolls 546 with the cam faces 554 and 556 on the rear ends of the gripper jaw carrying levers 528 and 530, the levers are actuated to close the welt gripping jaws on the welt, after which the continued movement of the knife bar advances the knife to sever the welt. The parts are then in the positions shown in Figs. 13 and 23 with the welt gripping jaws firmly gripping the severed end of the welt beyond the welt guide. When the knife bar has reached its advanced position, a pivoted latch 630 drops down behind the rear end of the knife bar and prevents the return movement of the bar. During the remainder of the rotation of the eccentric after the knife and gripper bars are advanced, the gear segment 580 is stationary, the slot 588 in the link 586 allowing the link to move independently of the gear segment at that time, thereby bringing the parts to the position shown in Fig. 13. The knife and gripper bars are held in advanced position as shown in this figure until the machine is started at the beginning of the next sewing operation upon the succeeding shoe. At the beginning of the next sewing operation, the latch 630 is lifted from behind the rear end of the knife bar, allowing the coiled spring 584 to actuate the gear segment 580 to retract the knife bar and gripper bar. The latch 630 is rigidly mounted upon and preferably formed integral with a lever 632 pivoted at 634 on the frame. Upon the forwardly extending arm of this lever is mounted a cam roll 636 adapted to be engaged by a peripheral cam on a cam disk mounted on the cam shaft of the machine. The engagement of this cam with the cam roll shortly after the machine is started lifts the rear end of the lever 632, thereby disengaging the latch 630 from behind the rear end of the knife bar. The movement of the gear segment under the action of the spring 584 is limited by the engagement of a stop lug 638 formed on the gear segment with an abutment 640 on the frame of the machine. In order to retard the movement of the gear segment 580 and the retracting movement of the knife bar and the gripper bar under the action of the spring 584 so that there will be no undue shock or vibration when the stop lug 638 brings up against the abutment 640, the gear segment 580 is connected by a link 642 with a piston 644 operating in a cylinder 646. The cylinder 646 is provided with an inlet valve 648 arranged to admit air freely into the cylinder but to prevent the exhaust of air therefrom, and with a check exhaust valve 650 which is constructed to allow the air to exhaust slowly as the piston moves downwardly in the cylinder. Through the co-operative action of the spring 584 and this pneumatic retarding device, the gear seg-

ment 580 is actuated to retract the knife bar and the gripper bar with a comparatively slow and gradual movement.

At the beginning of the sewing operation 5 upon the next shoe the latch 630 is lifted, the welt gripping jaws are released from gripping engagement with the free end of the welt and the welt gripping and cutting devices are retracted before the work is fed 10 in the first cycle of operations. In the present embodiment of the invention the free end of the welt is held in position with relation to the upper and insole by the welt gripping devices until the needle has entered the work 15 in the first cycle of operations after which the welt gripping and cutting devices are retracted. In order to hold the free end of the welt in proper relation to the shoe and prevent it from being drawn away from the 20 upper during the retracting movement of the needle or during the initial feed of the shoe, the machine is provided with a supplementary welt holder for engaging the free end of the welt and holding it in position 25 after the welt gripping jaws have released the welt. This welt holder engages the welt close to the point of operation of the needle on the advance side thereof in the direction of feed, so that during the retracting movement 30 of the needle, the welt is held on one side of the needle by the welt holder and on the other by the welt guide and thereby prevented from being drawn away from the upper. In order to prevent the welt from 35 being drawn away from the upper, particularly at the point where the loop of thread is passed through the welt by the strain exerted in drawing the welt through the welt guide during the initial feed of the shoe, 40 the welt holder is given a feeding movement during the initial feed of the shoe to draw the welt through the welt guide. This movement of the welt holder also assists in feeding the shoe. The welt 45 holder in the construction shown in the drawings consists of a dagger 652 adapted to penetrate the end of the welt and hold it in contact with the shoe. The dagger is held in retracted position except during the first 50 cycle of operations upon starting the machine. As the welt gripping and cutting devices are retracted just before the needle retracts from the work, the dagger is advanced into engagement with the welt and is moved 55 along with the shoe in the direction of feed during the initial feed of the shoe so as to draw the welt through the welt guide and assist in feeding the shoe. As the initial feed of the shoe is completed, the dagger is 60 retracted out of engagement with the welt and is held in retracted position during the remainder of the sewing operation. The dagger (see Figs. 22 and 23) is secured to the forwardly extending arm 654 of a 65 hanger 656 constructed in the form of a

yoke embracing a lever 658 and pivoted to swing on a vertical pivot pin 660 mounted in the lever. The lever 658 is pivoted upon a horizontal pivot pin 662 carried at the upper end of the swinging arm 664 mounted 70 on the shaft 352 which serves as a pivot for the arm 126 which supports the forward end of the welt guide. The lower end of the arm 664 carries an abutment screw 668 which engages a spring-pressed plunger constructed 75 and arranged in substantially the same manner as the plunger 130. With this construction it will be noted that the dagger is adjusted vertically with the welt guide by the adjustment of the block 128. The dagger is 80 moved in the direction of the feed by swinging the same about the vertical pivot pin or shaft 660. The supporting of the hanger 656 on the swinging arm 664 permits the dagger to be advanced into engagement with 85 the welt and to be retracted out of engagement therewith. In order to cause the dagger to move in a path substantially concentric with the welt guide, the lever 658 carries at its rear end a cam roll 670 engaging 90 a cam slot 672 in the fixed cam plate 110. The mechanism for advancing and retracting the dagger comprises a slide bar 674 mounted for forward and rearward movement in suitable guides in the frame of the 95 machine and having a slot 676 at its forward end in which engages the end of the roll 670. The rear end of the slide bar is connected by a link 678 (see Figs. 25 and 26) with the lower end of a lever 680 pivoted upon a shaft 100 105 682 mounted in the frame of the machine. The lever 680 is actuated to advance the dagger by means of a coiled spring 684 attached at one end to the lever and at the other to the frame. The slide bar 674 is held in retracted position except during a period immediately after the welt gripping and welt severing devices are retracted upon starting the machine by means of a latch 688 pivoted at 110 115 690 and adapted to engage in front of an upwardly projecting lug 692 formed on the link 678. The latch 688 is acted upon by a coiled spring 694 which operates to depress the latch into acting position. The latch 688 is lifted to allow the slide 674 to be advanced by the action of the spring 684 to engage the dagger 652 with the welt at the time that the latch 630 is lifted to allow the welt gripping and welt severing devices to 120 be retracted. In the construction shown the devices for lifting the latch 688 comprise a latch lifting arm 696 formed on a lever pivoted at 698 on an arm 700 which in turn is pivoted at 702 on the frame. The arm 700 is supported by a link 704 pivoted at 706 on the latch carrying lever 632 and having a hook at its lower end in which engages a pin 708 mounted in the arm 700. A spring 710 attached at one end to the arm 700 and at the other to the frame tends to pull the arm 700 125 130

downwardly. The arm 696 on the latch-lifting lever is formed with a hook 712 at its lower end adapted to engage beneath a lug 714 on the latch 688 and the lever is swung 5 on its pivot in a direction to engage the hook beneath the lug by a spring 716 attached at one end to an arm 718 on the latch-lifting lever and at the other to the arm 700. While the welt gripping and cutting devices are re- 10 tracted, the rear end of the lever 632 then being elevated and the lower edge of the latch 630 resting upon the upper edge of the knife bar 544, the hook on the arm 696 of the latch-lifting lever lies above the lug 714, 15 with the inclined face 720 on the hook resting against the inclined face 722 on the lug. As the welt gripping and cutting devices are advanced into operative positions the rear end of the lever 632 is depressed by the ac- 20 tion of the spring 710 and the hook on the arm 696 of the latch-lifting lever engages beneath the lug 714. Upon starting the ma- chine as the lever 632 is actuated to lift the latch 630 from behind the rear of the knife 25 bar the latch 688 is lifted from in front of the lug 692 by the hook on the latch-lifting lever and the lever 680 is then actuated by the spring 684 to advance the slide 674 and engage the dagger 652 with the end of the 30 welt. As the lever 680 moves forward the hook on the arm 696 of the latch-lifting lever is disengaged from beneath the lug 714 by the engagement of a lateral projection 724 formed on the lever 680 with the abutment 35 726 on the latch-lifting lever. The latch then drops down and rests upon the top of the lug 692.

After the initial feed of the work has taken place the slide bar 674 is retracted to 40 retract the dagger from engagement with the welt. To this end a lever 728 is mounted on the shaft 682 and carries a cam roll 730 arranged to engage a cam groove formed in a cam disc carried by the main shaft 18. 45 The lower end of the lever 728 carries a roll 732 adapted to engage the forwardly in- clined face of an adjustable block 734 mounted on the lever 680. When the slide bar 674 has advanced to engage the dagger 50 652 with the welt and after the initial feed of the work has taken place the lever 728 is swung in a direction to carry its lower arm rearwardly and through the engage- 55 ment of the roll 732 with the block 734 the lever 680 is actuated to retract the slide 674. As the slide reaches its retracted position, 60 the latch 688 drops down in front of the lug 692 and holds the parts in position. The parts of the mechanism for retracting 65 the slide are timed so that the slide 674 is retracted just as the initial feed of the shoe is completed.

In order to move the dagger in the direc- 70 tion of feed with the shoe during the initial feed of the shoe (see Figs. 22, 23 and 24),

the hanger 656 is formed with a rearwardly extending arm 736 carrying a roll 738 engag- 75 ing in a groove formed by the projecting flanges 740 on the sleeve 742 fixed to a slide rod 744. The rod 744 is mounted to slide 70 longitudinally in guides in the plate 746 and in the projection 748 on the frame, and is normally held against the plate 746 to maintain the dagger in its forward position in the direction of feed by a coiled spring 750 interposed between the sleeve 742 and the projection 748. Upon one end of the rod 744 is formed an enlargement or head 752 on which is pivoted upon a stud 754 a lever 756 carrying a catch 758 adapted to 80 hook over the forward or right-hand side (Fig. 24) of a plate or block 760 mounted on a downwardly extending arm 762 formed on the feed slide actuating lever 50, a spring 764 being arranged to actuate the lever 756 85 to throw the catch upwardly into position to engage the side of the plate 760. During the normal operation of the machine, and while the welt gripping and cutting devices are retracted, the catch 758 is held down 90 out of engagement with the plate 760. The engagement of the catch with the plate is controlled by two latches 766 and 768 (see Fig. 24) pivoted on the pin 770. From the time after the feeding devices have executed 95 their initial advancing and retracting move- ments upon starting the machine until the machine is stopped, the catch 758 is held out of engagement with the plate 760 by the right-hand end (Fig. 24) of the latch 766 100 which is adapted to engage behind an arm 772 formed on the lever 756. When the machine is finally brought to rest by the stopping mechanism, the feeding devices are in the positions which they assume after 105 having executed only part of their advance movement and when the machine is started these devices complete their advance move- ment at once, the arm 762 of the feed lever then swinging to the right (Fig. 24). As 110 the machine is started the welt gripping and severing devices are in advanced or oper- ating positions and the latch 768 is provided particularly to prevent the engagement of 115 the catch 758 with the forward side of the plate 760 and a consequent lateral actuation of the dagger 652 while the welt gripping and severing devices are in advanced positions which might result in breakage of the parts. While the latch 768 is somewhat 120 shorter than the latch 766 its length is suffi- cient to enable it to hold the catch out of engagement with the plate 760 when its acting end rests behind the arm 772. The end of the latch 768 is formed with a cam 125 face 774 which is engaged with the arm 772 on the catch lever as the end of the latch is depressed and the lever is thereby actuated to swing the catch downwardly out of en- gagement with the plate 760. A spring 776 130

is seated at its ends respectively in pockets formed in the left-hand ends of the latches, this spring acting while the right-hand end of the latch 766 is in operative position 5 behind the arm 772 to hold the left-hand end of the latch 768 against the stop face 778 on the frame. The right-hand end of the latch 768 is then held in elevated position above the arm 772. When the direction 10 of rotation of the cam shaft of the machine is reversed upon stopping the machine, the right-hand end of the latch 766 is lifted to disengage it from behind the arm 772 by means of a block or projection 780 carried 15 by the arm 782 fixed to a sleeve 784 mounted on the shaft 786. A second arm 788 is fixed to the opposite end of the sleeve 784, and is connected by a pin 790 with the link 332. The arm 782 is normally held in elevated 20 position by means of a spring 792 connected at one end to the arm and at the other to a point on the frame of the machine. Through the connection between the link 332 and the arm 788, the sleeve 784 is rocked in 25 a direction to depress the arm 782, upon the reversal of the rotation of the main shaft of the machine. During the downward movement of the arm 782 the block 780 strikes the upper side of the left-hand end of the latch 30 766 and depresses the same to lift the right-hand end of the latch from acting position, allowing the catch to be elevated by the spring 764 into engagement with the lower face of the plate 760 or into position to 35 engage the forward side of the plate depending on the position of the feed lever 53. To prevent the engagement of the catch 758 with the forward side of the plate 760, and a consequent lateral actuation of the dagger 40 652 while the welt gripping and severing devices are in advanced position, as the machine is started, the lever 528 upon which the upper welt gripping jaw is carried is formed with a lug 794 which, as the slide 45 532 moves forward, is positioned beneath the left-hand end of the latch 768, and as the levers 528 and 530 are actuated to close the welt gripping jaws the lug engages the under side of the left-hand end of the latch 50 768 and lifts the same, thereby depressing the right-hand end of the latch. During this movement of the latch 768 the cam face 774 on the right-hand end of the latch engages the arm 772 and turns the catch 55 lever to depress the catch and the continued movement of the latch carries its right end behind the arm, in which position it holds the catch 758 from engagement with the plate 760. The right-hand end of the latch 60 766 at this time rests upon the upper end of the arm 772 as shown in Fig. 24. As the levers 528 and 530 are actuated to open the welt gripping jaws the lug 794 on the lever 528 is lowered from engagement with the 65 under side of the latch 768, allowing the

left-hand end of this latch to be depressed by the spring 776 to disengage the right-hand end of the latch from behind the arm 772. The catch 758 is then elevated into position to engage the forward side of the 70 plate 760 when the feed lever reaches the proper position, and the rod 744 is moved longitudinally to swing the hanger 656 on the shaft 660 to move the dagger in the direction of feed with the shoe as the shoe 75 is fed.

As the machine is started, the block 780 on the arm 782 is lifted, and after the catch lever 756 has moved to the right (Fig. 24) a distance such that the arm 772 clears the right-hand end of the latch 766, this end of the latch is depressed into position behind the arm by the spring 776. When the rod 744 is returned to starting position under the action of the spring 750, the right-hand end 80 of the latch 766 engages the arm 772 and the catch is swung downwardly out of position to engage the plate 760.

In removing the shoe from the machine the operator manipulates the shoe to disengage 90 the channel guide from the channel, and then moves the shoe forward or in the direction of feed to draw the welt through the welt guide, so that the welt may be severed by the welt cutting devices a short distance from 95 the end of the inseam. Welt measuring devices are provided for limiting the extent to which the welt may be drawn through the welt guide, so that the welt will be severed always at a suitable uniform distance from 100 the end of the inseam, and connections are provided between the welt measuring mechanism and the latch 620 for lifting the latch to throw the eccentric actuating clutch into 105 operation to advance the welt gripping and cutting devices to grip and sever the welt through the movement of the welt measuring devices, produced by the drawing forward of the welt through the welt guide. This construction causes the welt gripping and cutting devices to be thrown into operation by the ordinary movements imparted to 110 the shoe in removing it from the machine, and enables the shoe to be quickly and easily freed from the machine. The welt measuring devices, in the construction shown, are arranged and controlled so that the welt gripping and cutting devices are inoperable 115 during the sewing operation, but are thrown into an operable condition by the reverse 120 movement imparted to the cam shaft of the machine upon stopping the machine.

As illustrated in the drawings (see Figs. 2, 3, 23, 27 and 28), the welt is led from the supply to the welt guide over a guide roll 125 796 which is arranged to turn freely on a stud 798 carried by one arm 800 of a welt measuring bell crank lever 802 pivoted on the stud 804, and yieldingly held in position during the sewing operation by a spring 805 130

attached at one end to the arm 800 of the bell crank and at the other to the frame. The movement of this lever is limited by means of a stud 806 which engages in a slot 808 formed in a projection 810 on the lever. The other arm 812 of this bell crank is connected by a link 814 with the arm 816 mounted on one end of a shaft 818. Upon the other end of this shaft is mounted the latch 620. Mounted on an arm 820 pivoted on a stud 822 is the movable jaw 824 of a welt clamping device, the other fixed jaw of which consists of a roll 826 eccentrically mounted on the stud 827. A guide 828 is also mounted on the stud 827 to engage the edge of the welt and prevent it from being displaced from between the welt clamping jaws. The arm 820 is loosely mounted on the stud 822, and the welt clamping jaw carried thereby is actuated to clamp the welt against the roll 826 by the movements of the arm 820 imparted by a lever 829, also pivoted on the stud 822, between the lower arm 830 of which and the arm 820 is interposed a spring 832 through which the arm 820 is yieldingly actuated. The clamping jaw 824 is normally held out of clamping position by the engagement of a lug 834 on the hub of the lever 829 with a projection 836 on the arm 820. To the horizontal arm 838 of the lever 829 is pivoted a link 840 having a slot 842 (see Fig. 29), at its lower end in which engages a pin 844 carried by the lower arm of the bell crank 338. The forward portion of this slot is formed to fit closely to the pin, so that there will be no lost motion between the lever 338 and the link when the pin is located in this part of the slot. The rear portion of the slot, however, is elongated so as to allow for a considerable lost motion between the bell crank 338 and the link, so that the link will not be actuated from the movements of the bell crank when the pin 844 occupies this portion of the slot. The pin is normally located in the forward portion of the slot, as shown in Fig. 29. With the pin occupying this position in the slot, as the lever 338 is swung downwardly by the reversal in the direction of rotation of the cam shaft of the machine, the link will be depressed and will actuate the lever 829 and the arm 820 to cause the clamping jaw 824 to clamp the welt against the roll 826. With the welt thus clamped intermediate the roll 796 and the supply, when the shoe is moved forward to draw the welt through the welt guide the welt measuring bell crank 802 is swung about the stud 804 by the pull on the welt. The movement of the bell crank is limited to limit the length of welt which may be drawn through the welt guide by this movement of the shoe by the engagement of the pin 806 with the upper end of the slot 808. The welt measuring bell crank lever therefore determines or measures the amount

of welt which may be drawn forward through the welt guide. The swinging movement of the welt measuring bell crank, caused by the forward movement of the welt, also lifts the latch 620 and throws the actuating mechanism for the welt gripping and severing devices into operation. 70

When the machine is started at the beginning of the next sewing operation, the bell crank 338 is swung upwardly, thereby elevating the link 840 and actuating the lever 829 and the arm 820 to release the jaw 824 from clamping engagement with the welt. The welt measuring bell crank 802 is returned to normal position by the action of the spring 805, and the latch 620 is again depressed into position to engage the dog 624. In order to ensure the restoration of the bell crank 802 to normal position, a strut 846 having its ends engaged in recesses respectively in a projection 848 on the bell crank and in a lug 850 on the lever 829 is provided. Through this strut as the lever 829 is swung about the stud 822, upon starting the machine the bell crank 802 is restored to normal position in the event that the spring 805 fails to act properly. An adjustable abutment screw 852 is mounted in the lug 850 to engage the end of the strut 846, and this abutment screw may be adjusted to secure the proper action of the strut on the lever 802. To prevent the lever 802 from being turned about the stud 804, and the welt gripping and severing devices thus thrown into operation by any undue strain on the welt during the sewing operation, a safety latch 854 is loosely mounted on the stud 822, and is provided with an arm 856 extending into position to engage the lug 858 on the bell crank 802. This safety latch is formed with a slot 860 in which engages a pin 862 mounted on the lever 829. During the sewing operation the end of the arm 856 lies in front of the lug 858 to prevent the bell crank 802 from turning about the shaft 804. As the lever 829 is turned about the stud 822 upon stopping the machine, the latch 854 is actuated through the engagement of the pin 862 with the lower end of the slot 860 to lift the arm 856 to the position shown in Fig. 27, to allow the bell crank 802 to be actuated in the manner above described. When the machine is started, the latch 854 is actuated to depress the arm 856 in front of the lug 858 through the engagement of the pin 862 with the upper end of the slot 860. 110

The latch 622 is mounted on a hollow shaft 864 through which the shaft 818 passes. The shaft 864 carries an arm 866 on which is mounted a cam roll 868 arranged to engage a peripheral cam on a cam disc mounted on the main shaft 18 of the machine. Through the engagement of this cam with the cam roll 868, the latch 622 is lifted out of engagement. 130

ment with the dog 624 during the first revolution of the cam shaft upon starting the machine, allowing the clutch which actuates the eccentric sleeve 600 to be engaged to rotate the sleeve. The eccentric sleeve, however, makes only a relatively small part of a revolution at this time, the clutch being again disengaged through the engagement of the latch 620 which has then been lowered into operative position with the dog 624.

In case the operator desires to run the machine or to draw the welt from the supply without throwing the devices for severing the welt and for holding its free end into operation, he swings the link 840 forward so as to locate the pin 844 in the elongated portion of the slot 842. This will render the mechanism for actuating the clamping jaw 824 to clamp the welt upon stopping the machine inoperative, so that when the machine is at rest the welt may be drawn freely over the roll 796 without throwing the welt gripping and severing devices into operation.

The devices for severing the thread between the supply and the work, and for holding the end of the thread leading from the supply after the thread is severed (see Figs. 1, 22, 30, 31, 32), comprise a fixed thread cutting knife and a thread gripping device provided with relatively movable thread clamping jaws which are opened to receive the thread upon stopping the machine, and which are closed upon the thread to grip the same as the machine is started. In the construction shown, the thread gripping device comprises a fixed gripping jaw 870 carried by a plate 872 secured to the frame, and a movable gripping jaw 874 carried by a block mounted on the longitudinally movable slide rod 876. The thread gripping jaws are located immediately above the looper and thread arm in convenient position for the operator to place the thread between the jaws by a simple movement of the shoe. The fixed jaw is provided with a hooked end 878 to catch the thread as the shoe is drawn forwardly, and thus assist the operator in placing the thread between the jaws. The rod 876 is moved rearwardly to open the jaws upon stopping the machine by means of an arm 880 carried by the sleeve 784. The arm 880 is formed with a slot 882 in which engages a pin 884 mounted in the rear end of the slide rod 876. As the sleeve 784 is rocked upon the reversal of the direction of rotation of the cam shaft of the machine, the arm 880 is actuated to retract the slide rod 876 and thereby open the thread gripping jaws. The sleeve 784 is turned in the opposite direction as the machine is started, through the action of the coiled spring 792 upon the arm 782, and the slide rod 876 is then advanced to carry the movable thread gripping jaw 874 toward the fixed jaw 870

by the action of a coiled spring 886 attached at one end to the slide rod 876, and at the other to one arm of a bell crank lever 888 pivoted at 890 on the frame of the machine. The other arm of the bell crank 888 carries an abutment screw 892 arranged to engage an abutment 894 on the frame. The tension of the spring 886 may be adjusted by the adjustment of the abutment screw 892 in the arm of the bell crank. The adjustment of this screw regulates the pressure of the movable jaw 874 of the thread clamping device upon the thread, and thus regulates the tension exerted by the clamping device upon the thread during the formation of the first few stitches.

The thread cutting knife indicated at 896 is mounted above the thread-gripping device in position such that when the thread is passed between the thread-gripping jaws 870 and drawn over the edge of the knife to sever the same, as shown in Figs. 30, 31 and 32, a sufficient length of thread will be left projecting beyond the thread gripping jaws to prevent the thread from pulling from between the gripping jaws until the first stitch has been completed. The knife is secured to the frame by means of a bolt 898.

The thread gripping mechanism of the machine above described forms the subject matter of a divisional application Serial No. 252,968, filed Sept. 6, 1918; the tension mechanism of the machine above described forms the subject matter of a divisional application Serial No. 252,969, filed Sept. 6, 1918, 100 on which Patent No. 1,391,398, issued on Sept. 20, 1921; and the driving and stopping mechanism of the machine above described forms the subject matter of a divisional application, Serial No. 256,583, filed Oct. 2, 1918, on which Patent No. 1,533,159, issued on Oct. 12, 1920.

Although the various features of the invention have been illustrated and described as embodied in a welt shoe sewing machine for sewing welts and uppers to the insoles of welted shoes, it is to be understood that except as defined in the claims the invention is not limited to any particular machine or type of machine. It is also to be understood that the invention is not limited to the particular construction of the illustrated embodiment thereof, but that it may be embodied in other forms within the scope of the claims.

Having explained the nature and object of the invention, and having specifically described a machine embodying the invention in its preferred form, what is claimed is:

1. A welt shoe sewing machine having, in combination, stitch forming mechanism including a curved hook needle, devices for gripping the free end of the welt after the welt is severed, and a welt holder arranged to engage one side only of the welt end and

hold it in position against the upper of the shoe until it is attached to the shoe by one or more stitches.

2. A welt shoe sewing machine having, in combination, stitch forming mechanism including a curved hook needle, devices for holding the extreme end of the severed welt, and a supplementary welt holder arranged to engage the welt end at a point intermediate said devices and the needle and acting to hold the welt end in sewing position until it is attached to the shoe by one or more stitches.

3. A welt shoe sewing machine having, in combination, stitch forming mechanism including a curved hook needle, welt holding devices fixed in the direction of feed for holding the free end of the welt after the welt is severed at the completion of a seam, a supplementary welt holder movable in the direction of feed for holding the welt end during the feeding of the shoe at the beginning of the sewing of a seam, and means for throwing the welt holding devices out of operation and the supplementary welt holder into operation prior to the initial feed of the shoe.

4. A welt shoe sewing machine having, in combination, stitch forming mechanism including a curved hook needle, welt holding devices for holding the free end of the welt after the welt is severed at the completion of a seam, and a supplementary welt holder movable in the direction of feed for holding the welt end during the feeding of the shoe at the beginning of the sewing of a seam.

5. A welt shoe sewing machine having, in combination, stitch forming mechanism including a curved hook needle, welt cutting devices for severing the welt adjacent the shoe after a seam is sewn, welt holding devices for holding the welt during the action of the welt cutting devices, and a supplementary welt holder for holding the welt end in position until it is attached to the shoe by one or more stitches.

6. A welt shoe sewing machine having, in combination, stitch forming mechanism including a curved hook needle, welt cutting devices for severing the welt adjacent the shoe after a seam has been sewn, welt holding means fixed in the direction of feed for holding the free end of the severed welt, a supplementary welt holder movable in the direction of feed for holding the welt end after it is released by said welt holding means, arranged to hold the welt end in sewing position until it is attached to the shoe by one or more stitches, and means for withdrawing said welt holding means from operation and for throwing the supplementary welt holder into operation prior to the initial feed of the shoe.

7. A welt shoe sewing machine having, in combination, stitch forming mechanism in-

cluding a curved hook needle, welt severing and holding means for severing the welt adjacent the shoe after a seam has been sewn, and for holding the free end of the welt after the welt is severed, and a supplementary welt holder movable in the direction of feed for holding the welt end in sewing position with relation to the shoe during the initial feed of the shoe.

8. A welt shoe sewing machine having, in combination, stitch forming mechanism including a curved hook needle, devices for severing the welt adjacent the shoe after the seam has been sewn, welt gripping devices for holding the free end of the welt during the action of the welt severing devices and until a new seam is started, a supplementary welt holder arranged to engage one side only of the welt at a point intermediate the welt gripping devices and the needle for holding the welt against the upper during the beginning of the sewing of a seam, and means for supporting said welt holder for movement in the direction of feed during the feeding of the shoe.

9. A welt shoe sewing machine having, in combination, stitch forming mechanism including a curved hook needle, two independently acting welt holders for holding the free end of the severed welt until the welt end is attached to the shoe by one or more stitches, and means for throwing the welt holders into and out of action at different times.

10. A welt shoe sewing machine having, in combination, stitch forming mechanism including a curved hook needle, welt cutting devices, a welt holder for holding the welt during the action of the welt cutting devices, and for holding the free end of the welt after it is severed, and a supplementary welt holder arranged to engage the welt at a point intermediate the first welt holder and the needle for holding the free end of the welt in position with relation to the shoe until it is attached to the shoe by one or more stitches.

11. A welt shoe sewing machine having, in combination, stitch forming mechanism including a curved hook needle, two independently acting welt holders arranged to engage the welt at different points between the extreme end of the welt and the needle, and means for moving the welt holders into and out of operating positions.

12. A welt shoe sewing machine having, in combination, stitch forming mechanism including a curved hook needle, welt severing and holding devices, positively acting mechanism for advancing said devices into operation, a spring for withdrawing said devices from operation, and a dash pot for retarding the withdrawing movement of said devices.

13. A welt shoe sewing machine having,

- in combination, stitch forming mechanism including a curved hook needle, welt cutting and holding devices, positively acting means for advancing the welt cutting and holding devices into operation, a latch for holding the welt cutting and holding devices in advanced position, means for lifting the latch, and spring actuated mechanism for retracting the welt cutting and holding devices.
14. A welt shoe sewing machine having, in combination, stitch forming mechanism including a curved hook needle, a welt holder for holding the free end of the severed welt, a latch for retaining the welt holder in retracted position, means for lifting the latch, a spring for advancing the welt holder into operating position upon the lifting of the latch, and positively acting means for retracting the welt holder.
15. A welt shoe sewing machine having, in combination, stitch forming mechanism including a curved hook needle, a welt cutting and holding devices, an intermittently operating slow speed clutch and connections for advancing the welt cutting and holding devices from the clutch, a latch for holding the welt cutting and holding devices in advanced position, means for lifting the latch, and a spring for retracting the welt cutting and holding devices upon the lifting of the latch.
16. A welt shoe sewing machine having, in combination, stitch forming mechanism: including a curved hook needle, a welt holder, a forwardly and rearwardly movable carrier therefor, a support upon which the carrier is pivoted for oscillation in one plane to carry the welt holder in the direction of feed, and also for oscillation in another plane substantially parallel with the plane of the needle, means for advancing and retracting the carrier, and means for oscillating the carrier in the second plane during its forward and rearward movements.
17. A welt shoe sewing machine having, in combination, stitch forming mechanism including a curved hook needle, a welt holder, a movable carrier therefor, a forwardly and rearwardly swinging arm upon which the carrier is pivoted for oscillation in one plane to carry the welt holder in the direction of feed and also for oscillation in a plane substantially parallel with the plane of the needle, means for advancing and retracting the carrier, and means for oscillating the carrier in the second plane during its forward and rearward movements.
18. A welt shoe sewing machine having, in combination, stitch forming mechanism including a curved hook needle, a welt guide, a welt holder for holding the free end of the severed welt projecting beyond the welt guide, a forwardly and rearwardly
- movable carrier therefor, a support upon which the carrier is pivoted for oscillation in a plane substantially parallel with the plane of the needle, means for advancing and retracting the carrier, and means for oscillating the carrier during its forward and rearward movements.
19. A welt shoe sewing machine having, in combination, stitch forming mechanism including a curved hook needle, a welt guide, a welt holder for holding the free end of the severed welt projecting beyond the welt guide, a forwardly and rearwardly movable carrier therefor, a support upon which the carrier is pivoted for oscillation in a plane substantially parallel with the plane of the needle, means for advancing and retracting the carrier, and a fixed cam for oscillating the carrier during its forward and rearward movements.
20. A welt shoe sewing machine having, in combination, stitch forming mechanism including a curved hook needle, a welt holder, a forwardly and rearwardly movable carrier therefor, a support upon which the carrier is pivoted for oscillation in one plane to carry the welt holder in the direction of feed, and also for oscillation in a plane substantially parallel with the plane of the needle, a slide connected with the carrier for advancing and retracting the carrier, a second slide connected with the carrier for oscillating the carrier in the first plane, and a fixed cam acting on the carrier for oscillating the carrier in the second plane.
21. A welt shoe sewing machine having, in combination, stitch forming mechanism including a curved hook needle, a welt holder, a forwardly and rearwardly movable carrier therefor, a support upon which the carrier is pivoted for oscillation in one plane to carry the welt holder in the direction of feed, and also for oscillation in a plane substantially parallel with the plane of the needle, and means for advancing and retracting the carrier and for oscillating the carrier in both planes.
22. A welt shoe sewing machine having, in combination, stitch forming mechanism including a curved hook needle, a welt holder, a carrier therefor, mounted for movement to carry the welt holder in the direction of feed, a continuously oscillating lever, a laterally movable slide, a connection between the carrier and the slide for actuating the carrier from the slide, a catch for intermittently connecting the slide with the lever, and means for controlling the operation of the catch.
23. A welt shoe sewing machine having, in combination, stitch forming mechanism including a curved hook needle, a welt holder, a carrier therefor mounted for movement to carry the welt holder in the direction of feed,

shoe feeding devices comprising an oscillating lever, a laterally movable slide, a connection between the carrier and slide for actuating the carrier from the slide, a catch for connecting the slide with the lever, one or more latches for controlling the operation of the catch, and means for throwing out the latches to permit the catch to connect the slide with the lever at the beginning of the 10 sewing of a seam.

24. A welt shoe sewing machine having, in combination, stitch forming mechanism including a curved hook needle, a welt holder, a carrier for the welt holder mounted 15 for movement to carry the welt holder in the direction of feed, shoe feeding devices, connecting mechanism for actuating the carrier from the shoe feeding devices, one or more latches for preventing the actuation of the 20 carrier from the shoe feeding devices, and means for throwing out the latches to permit the actuation of the carrier from the shoe feeding devices at the beginning of the 25 sewing of a seam.

25. A welt shoe sewing machine having, in combination, stitch forming mechanism including a curved hook needle, a welt holder, a carrier therefor, shoe feeding devices, connecting mechanism for actuating the carrier 30 from the feeding devices, a latch for preventing the actuation of the carrier from the feeding devices during the sewing of the seam after the first cycle of operations, a second latch for preventing the actuation of 35 the carrier from the feeding devices before the thread of the first stitch is drawn through the work, means for throwing out the first latch after the seam is completed, and means for throwing out the second latch 40 after the machine is started.

26. A welt shoe sewing machine having, in combination, stitch forming mechanism including a curved hook needle, welt cutting and holding devices, a supplementary welt 45 holder, a carrier for the welt holder mounted for movement to carry the welt holder in the direction of feed, shoe feeding devices, connecting mechanism for actuating the 50 carrier from the shoe feeding devices, a latch for preventing the actuation of the carrier from the shoe feeding devices while the welt cutting and holding devices are in advanced positions, and means for throwing 55 out the latch when the welt cutting and holding devices are retracted.

27. A welt shoe sewing machine having, in combination, stitch forming mechanism including a curved hook needle, welt cutting and holding devices, a supplementary welt 60 holder, a carrier for the welt holder mounted for movement to carry the welt holder in the direction of feed, shoe feeding devices, connecting mechanism for actuating 65 the carrier from the shoe feeding devices,

a latch for preventing the actuation of the carrier from the shoe feeding devices while the welt cutting and holding devices are in advanced positions, a second latch for preventing the actuation of the carrier from the 70 shoe feeding devices after the first cycle of operations, and means for controlling the latches.

28. A welt shoe sewing machine having, in combination, stitch forming mechanism including a curved hook needle, welt cutting and holding devices, a supplementary welt holder, a carrier for the welt holder mounted for movement to carry the welt holder in the direction of feed, shoe feeding devices, connecting mechanism for actuating the carrier from the shoe feeding devices, a latch for preventing the actuation of the carrier from the shoe feeding devices while the 75 welt cutting and holding devices are in advanced positions, a second latch for preventing the actuation of the carrier from the shoe feeding devices after the first cycle of operations, and means for throwing out the first latch when the welt cutting and holding devices are retracted, and for throwing out the second latch after the seam is completed.

29. A welt shoe sewing machine having, in combination, stitch forming mechanism including a curved hook needle, welt cutting and gripping devices comprising a cutter bar, a gripper bar, welt gripping jaws mounted on the gripper bar, automatically acting means for advancing and retracting 95 the cutter bar, and means actuated by the movement of the cutter bar for advancing and retracting the gripper bar and for relatively actuating the welt gripping jaws.

30. A welt shoe sewing machine having, in combination, stitch forming mechanism including a curved hook needle, welt cutting and gripping devices comprising a gripper bar, a cutter bar, automatically acting means for advancing and retracting the cutter bar, 105 and connections between the cutter bar and gripper bar for advancing the gripper bar with the cutter bar from the movements of the cutter bar during the first part of the advancing movement of the cutter bar and the last part of the retracting movement of the cutter bar arranged to permit the cutter bar to move independently of the gripper bar during the last part of the advancing movement of the cutter bar and during the 110 first part of the retracting movement of the cutter bar.

31. A welt shoe sewing machine having, in combination, stitch forming mechanism including a curved hook needle, welt cutting and gripping devices comprising a gripper bar, a cutter bar, a pivoted abutment mounted on one of the bars, an abutment carried by the other bar arranged to engage the pivoted abutment to move the gripper 125 130

bar from the cutter bar, and a stop for preventing the pivoted abutment from moving out of the way of the other abutment during the first part of the advancing movement of the cutter bar arranged to permit the pivoted abutment to move out of the way of the second abutment during the last part of the advancing movement of the cutter bar.

32. A welt shoe sewing machine having, in combination, stitch forming mechanism including a curved hook needle, welt cutting and gripping devices comprising a gripper bar, welt gripping jaws carried by the gripper bar, a lever pivoted to the gripper bar upon which lever one of the welt gripping jaws is mounted, a cutter bar, means for advancing and retracting the cutter bar, an abutment carried by the cutter bar, an abutment carried by the lever arranged to be engaged by the first abutment when the gripping jaws are open and to be carried out of the path of the first abutment by the movement of the lever to close the gripping jaws, and means for holding the lever in open-jaw position during the first part of the advancing movement of the cutter bar, so that the abutments are engaged and the gripper is advanced from the movement of the cutter bar, arranged to permit the lever to swing to close the gripping jaws when the gripper bar has reached its advanced position so as to allow the cutter bar to advance independently of the gripper bar.

33. A welt shoe sewing machine having, in combination, stitch forming mechanism including a curved hook needle, welt cutting and gripping devices comprising a gripper bar, a cutter bar, automatically acting means for advancing and retracting the cutter bar, and connections for actuating the gripper bar from the movements of the cutter bar.

34. A welt shoe sewing machine having, in combination, stitch forming mechanism including a curved hook needle, welt cutting and gripping devices comprising a cutter bar, a gripper bar, welt gripping jaws carried by the gripper bar, a lever upon which one of the jaws is mounted, and a device carried by the cutter bar adapted to engage the lever to advance the gripper bar with the cutter bar during the first part of the advancing movement of the cutter bar, and to actuate the lever to close relatively the welt gripping jaws during the last part of the advancing movement of the cutter bar.

35. A welt shoe sewing machine having, in combination, stitch forming mechanism including a curved hook needle, welt cutting and gripping devices comprising a cutter bar, a gripper bar, welt gripping jaws carried by the gripper bar, a lever pivoted on the gripper bar upon which one of the welt gripping jaws is carried, an abutment carried by the cutter bar arranged to engage the lever to move the gripper bar with the

cutter bar during the first part of the advancing movement of the cutter bar, and a stop engaged by the lever to hold the gripper bar stationary during the first part of the retracting movement of the cutter bar.

70

36. A welt shoe sewing machine having, in combination, stitch forming mechanism including a curved hook needle, a welt measuring lever, a welt gripping device independent of the lever for gripping the welt between the supply and the lever, and means for actuating the gripping device to grip and release the welt.

75

37. A welt shoe sewing machine having, in combination, stitch forming mechanism including a curved hook needle, welt cutting and holding devices, means for actuating said devices to sever and hold the welt, a welt measuring lever, a connection between the welt measuring lever and said actuating means for throwing the actuating means into operation, a welt gripping lever independent of the welt measuring lever for gripping the welt between the supply and the welt measuring lever, a latch for preventing the actuation of the welt measuring lever, and a common actuator for actuating the welt gripping lever to grip and release the welt and for throwing the latch out of and into operative position with relation to the welt measuring lever.

90

38. A welt shoe sewing machine having, in combination, stitch forming mechanism including a curved hook needle, welt cutting and holding devices, means for actuating said devices to sever and hold the welt, a welt measuring lever, a welt guiding device mounted on one arm of the lever, a connection between the other arm of the lever and said actuating means for throwing the actuating means into operation from the movement of the lever, a welt gripping device independent of the lever for gripping the welt between the welt measuring lever and the supply, and means for actuating the gripping device to grip and release the welt.

100

39. A welt shoe sewing machine having, in combination, stitch forming mechanism including a curved hook needle, welt cutting and holding devices, means for actuating said devices to sever and hold the welt, a welt measuring lever, a welt guiding device carried by one arm of the lever, a connection between the other arm of the lever and said actuating means for throwing the actuating means into operation from the movement of the lever, a welt gripping lever independent of the welt measuring lever pivoted on an axis substantially parallel with the axis of the welt measuring lever, a latch pivoted co-axially with the welt gripping lever for preventing movement of the welt measuring lever, a lever for actuating the welt gripping lever and the latch pivoted co-axially therewith, and a connection between the last

105

110

115

120

125

130

lever and the welt measuring lever for actuating the welt measuring lever therefrom.

40. An inseam shoe sewing machine having, in combination, stitch forming mechanism including a curved hook needle, a work rest, a work rest controller bar, a cam actuated lever, and means operated by the lever for locking the bar in advanced position from forward or rearward movement and for retracting the bar.

41. An inseam shoe sewing machine having, in combination, stitch forming mechanism including a curved hook needle, a work rest, a spring to force the work rest yielding into engagement with the work, and means for forcing the work rest positively against the work and locking it from forward or rearward movement and for retracting the work rest during each cycle of operation.

42 An inseam shoe sewing machine having, in combination, stitch forming mechanism including a curved hook needle, a work rest, a work rest controller bar, clutch devices mounted on the bar for locking the work rest against forward movement, clutch devices mounted on the bar for locking the work rest against retracting movement, and a common actuator for said clutch devices mounted on the bar.

43. An inseam shoe sewing machine having, in combination, stitch forming mechanism including a curved hook needle, a work rest, a work rest controller bar, clutch devices mounted on the bar for locking the work rest against forward movement, clutch devices mounted on the bar for locking the work rest against retracting movement, and a common actuator for said clutch devices mounted on the bar and acting when moved in one direction to cause said clutch devices to clutch the bar.

44. An inseam shoe sewing machine having, in combination, stitch forming mechanism including a curved hook needle, a work rest, a work rest controller bar, clutch devices mounted on the bar, and a clutch actuator mounted on the bar and acting when moving in one direction to cause the clutch devices to clutch and lock the bar from forward or rearward movement, and when moving in the opposite direction to cause the clutch devices to clutch and retract the bar.

45. An inseam shoe sewing machine having, in combination, stitch forming mechanism including a curved hook needle, a work rest, a work rest controller bar, means for yieldingly forcing the bar toward the work to bring the work rest into engagement with the work, and means for gripping the bar and forcing it forward to force the work rest against the work and for locking it from forward or rearward movement.

46. An inseam shoe sewing machine having, in combination, stitch forming mecha-

nism including a curved hook needle, a work rest, a work rest controller bar, clutch devices mounted on the bar for clutching and locking the bar against forward or rearward movement, clutch devices mounted on the bar for clutching and retracting the bar, and a common actuator for said clutch devices.

47. An inseam shoe sewing machine having, in combination, stitch forming mechanism including a curved hook needle, a work rest, a work rest controller bar, a cam lever, a spring for advancing the bar, a connection between the cam lever and the bar for controlling the forward movement of the bar, clutch devices for clutching and locking the bar from forward or rearward movement, clutch devices for clutching and retracting the bar, and a common actuator for said clutch devices carried by the cam lever.

48. A welt shoe sewing machine having, in combination, stitch forming mechanism including a curved hook needle, a welt guide, a welt holder for holding the free end of the severed welt projecting beyond the welt guide, a carrier therefor movable toward and from the shoe, a pivotally mounted arm supporting the carrier, and a yielding stop for the arm to limit the forward movement of the carrier.

49. A welt shoe sewing machine having, in combination, stitch forming mechanism including a curved hook needle, a welt guide, a welt holder for holding the free end of the severed welt projecting beyond the welt guide, a carrier therefor, a pivotally mounted arm supporting the carrier, and means for adjusting the arm to adjust the position of the welt holder.

50. A welt shoe sewing machine having, in combination, stitch forming mechanism including a curved hook needle, a welt holder for holding the free end of the severed welt, a carrier therefor, a forwardly and rearwardly movable support upon which the carrier is pivoted for oscillation in one plane to carry the welt holder in the direction of feed, a pivotally mounted arm upon which the support is pivoted for oscillation in a plane substantially parallel with the plane of the needle, means for oscillating the carrier, and a stationary cam acting on the support to impart oscillating movements thereto during the forward and rearward movements of said support.

51. A welt shoe sewing machine having, in combination, stitch forming mechanism including a curved hook needle, welt cutting and holding devices, means for actuating said devices to sever and hold the welt, a welt gripper for gripping the welt between the shoe and the supply, a welt engaging device arranged to engage the welt intermediate the welt gripper and the shoe and

operation on the work by the movement of the actuating slide independently of the second slide in the first direction.

60. A shoe machine having, in combination, operating means, an actuating slide, a second slide, means operating to connect positively the second slide with the actuating slide during the first part of the movement of the actuating slide in one direction and during the last part of the movement of the actuating slide in the reverse direction, and to hold positively the second slide stationary during the last part of the movement of the actuating slide in the first direction and during the first part of the movement of the actuating slide in the reverse direction, and devices for operating on the work carried by at least one of the slides arranged to be moved into operating position by the movement of the slides together in the first direction, and to be actuated to perform their operation on the work by the movement of the actuating slide independently of the second slide in the first direction.

61. A shoe machine having, in combination, operating means, a cutter slide, a cutting device carried by the slide, a second slide, a coupling device, and means for operating and controlling the coupling device to cause the same to connect and disconnect the slides.

62. A shoe machine having, in combination, operating means, a cutter slide, a cutting device carried by the slide, a second slide, a coupling device, means for operating and controlling the coupling device to cause the same to connect and disconnect the slides, and to hold one of the slides stationary during movement of the other slide.

63. A shoe machine having, in combination, operating means, an actuating slide, a second slide, abutments carried by the respective slides and guides through which the slides move, constructed and arranged to cooperate to cause the second slide to be actuated positively from the actuating slide during the first part of the forward movement of the actuating slide and during the latter part of the rearward movement of the actuating slide, and to hold the second slide stationary during the latter part of the forward movement of the actuating slide and during the first part of the rearward movement of the actuating slide, and devices for operating on the work carried by at least one of the slides and arranged to be moved into operating position by the forward movement of the slides together, and to be actuated to perform their operation on the work by the forward movement of the actuating slide independently of the second slide.

64. A shoe machine having, in combina-

tion, operating means; an actuating slide, a second slide, abutments carried by the respective slides; and guides through which the slides move, constructed and arranged to connect positively the second slide for movement with the actuating slide during the first part of the movement of the actuating slide in one direction and to hold positively the second slide stationary during the first part of the movement of the actuating slide in the reverse direction, and devices for operating on the work carried by at least one of the slides arranged to be moved into operating position by the movement of the slides together in the first direction and to be actuated to perform their operation on the work by the movement of the actuating slide independently of the second slide in the first direction.

65. A shoe machine having, in combination, operating means, an actuating slide, a second slide, a coupling device movably mounted on one of the slides, controlled by the movement of the slides and operating to connect and disconnect the slides, and devices for operating on the work carried by at least one of the slides and arranged to be moved into operating position by the movement of the slides together and to be actuated to perform their operation during relative movement of the slides.

66. A shoe machine having, in combination, operating means, an actuating slide, a second slide, a coupling device movably mounted on one of the slides, controlled by the movement of the slides and operating to connect and disconnect the slides, and to hold one of the slides stationary during movement of the other slide, and devices for operating on the work carried by at least one of the slides arranged to be moved into operating position by the movement of the slides together and to be actuated to perform their operation during relative movement of the slides.

67. A welt shoe sewing machine having, in combination, stitch forming mechanism including a curved hook needle, a welt holder for holding the end of the welt in position to be attached to the shoe, operative only during the first part of a seam formation, and machine controlled means for advancing and retracting the welt holder.

68. A welt shoe sewing machine having, in combination, stitch forming mechanism including a curved hook needle, welt cutting and gripping devices, means for advancing the welt cutting and gripping devices, a supplementary welt holder, a spring for advancing the welt holder, a latch for holding the welt holder in retracted position, means for lifting the latch rendered operative as the welt cutting and gripping devices are advanced, and means for operating the latch

adapted to be actuated by a forward pull on the welt, connections between the welt engaging device and said actuating means for throwing the actuating means into operation 5 from the movement of said device, and automatically acting mechanism for actuating the welt gripper to grip the welt upon stopping the machine, comprising a link having a slot at one end, and a pin engaging in the 10 slot constructed and arranged to enable the link and pin to be operatively connected and to be disconnected by swinging the link about its opposite end.

52. A welt shoe sewing machine having, 15 in combination, stitch forming mechanism including a curved hook needle, welt cutting and holding devices, mechanism for actuating said devices to sever and hold the welt, devices operated by a forward pull on the 20 welt for throwing said actuating mechanism into operation, means acting automatically to render the latter devices operative upon stopping the machine, comprising a connection having provision for adjustment to render the latter devices inoperative when the 25 machine is at rest.

53. A welt shoe sewing machine having, in combination, stitch forming mechanism including a curved hook needle, welt cutting 30 and holding devices, means for actuating said devices to sever and hold the welt, mechanism operated by a forward pull on the welt for throwing said actuating means into operation, means arranged to act automatically to render said mechanism operative upon stopping the machine, comprising a link having a slot at one end, and a pin engaging in the slot constructed and arranged to enable the link and pin to be 35 operatively connected and to be disconnected by swinging the link about its opposite end.

54. A welt shoe sewing machine having, in combination, stitch forming mechanism including a curved hook needle, welt cutting 45 and holding devices, a welt feeding supplementary welt holder, and means for actuating the welt holder to engage it with the welt and to feed the welt forward during the first cycle of operations upon starting 50 the machine.

55. A shoe machine having, in combination, operating means, a gripper slide, gripping devices carried by the slide, a second slide, a coupling device, and means 55 for operating and controlling the coupling device to cause the same to connect and disconnect the slides.

56. A shoe machine having, in combination, operating means, a gripper slide, 60 gripping devices carried by the slide, a second slide, a coupling device, and means for operating and controlling the coupling device to cause the same to connect and disconnect the slides and to hold one of the

slides stationary during movement of the 65 other slide.

57. A shoe machine having, in combination, operating means, an actuating slide, a second slide, a coupling device, means for operating and controlling the coupling device to cause the same to connect the second slide with the actuating slide during the first part of the movement of the actuating slide in one direction, to disconnect the second slide from the actuating slide during the 75 last part of the movement of the actuating slide in said direction, to hold the second slide stationary during the first part of the reverse movement of the actuating slide, and to release the second slide for movement 80 with the actuating slide during the last part of the reverse movement of the actuating slide, and devices for operating on the work carried by at least one of the slides, arranged to be moved into operating position 85 by the movement of the slides together in the first direction, and to be actuated to perform their operation on the work by the movement of the actuating slide independently of the second slide in the first direction. 90

58. A shoe machine having, in combination, operating means, an actuating slide, a second slide, a coupling device, means for operating and controlling the coupling device to cause the same to connect the second 95 slide with the actuating slide during the first part of the movement of the actuating slide in one direction, and to hold the second slide stationary during the first part of the movement of the actuating slide in the reverse direction, and devices for operating on the work carried by at least one of the slides, arranged to be moved into operating 100 position by the movement of the slides together in the first direction, and to be actuated to perform their operation on the work by the movement of the actuating slide independently of the second slide in the first direction. 105

59. A shoe machine having, in combination, operating means, an actuating slide, a second slide, means operating to connect positively the second slide with the actuating slide during the first part of the movement of the actuating slide in one direction, 115 and during the last part of the movement of the actuating slide in the reverse direction, and to allow the actuating slide to move independently of the second slide during the last part of the movement of the 120 actuating slide in the first direction, and during the first part of the movement of the actuating slide in the reverse direction, and devices for operating on the work carried by at least one of the slides, arranged to be 125 moved into operating position by the movement of the slides together in the first direction, and to be actuated to perform their

lifting means and for retracting the welt cutting and gripping devices upon starting the machine.

69. A welt shoe sewing machine having, in combination, stitch forming mechanism including a curved hook needle, a welt engaging device, a spring for moving said device in one direction, and a dash-pot for retarding the movement of said device under 10 the action of the spring.

70. An inseam shoe sewing machine having, in combination, stitch forming mechanism including a curved hook needle, a work rest, a work rest controller bar, a roll clutch 15 for locking the bar against forward movement, a roll clutch for locking the bar against rearward movement, and means for actuating and controlling the clutches.

71. An inseam shoe sewing machine having, in combination, stitch forming mechanism including a curved hook needle, a work rest, a work rest controller bar, a roll clutch for locking the bar against forward movement, a roll clutch for locking the bar 25 against rearward movement, a roll clutch for retracting the bar, and a common actuator for said clutches.

72. An inseam shoe sewing machine having, in combination, stitch forming mechanism including a curved hook needle, a work rest, a work rest controller bar, a roll clutch for locking the bar against forward movement, a roll clutch for locking the bar against rearward movement, and a common 35 actuator for said clutches.

73. A welt shoe sewing machine having, in combination, stitch forming mechanism including a curved hook needle, a welt holder for holding the free end of the welt 40 operative only during the first part of a seam formation, means for advancing and retracting the welt holder, and mechanism for causing the welt holder to move in a path substantially concentric with the path 45 of the needle during its forward and rearward movements.

74. A welt shoe sewing machine having, in combination, stitch forming devices, including a curved hook needle, welt cutting 50 and holding devices, means for throwing said devices into operation and means by which, at the will of the operator, said devices may be prevented from being thrown into operation.

55 75. A welt shoe sewing machine having, in combination, stitch forming devices includ-

ing a curved hook needle, welt cutting and holding devices, mechanism arranged to be actuated by a pull on the welt to throw the welt cutting and holding devices into operation, and means by which the operator may control the operativeness of said mechanism. 60

76. A welt shoe sewing machine having, in combination, stitch forming mechanism including a curved hook needle, welt cutting 65 and holding devices, mechanism for actuating said devices to sever and hold the welt, controlling mechanism arranged to be operated by a pull on the welt for throwing said actuating mechanism into operation, 70 mechanism for rendering normally said controlling mechanism operative upon stopping the machine, and means by which said controlling mechanism may be rendered inoperative at the will of the operator when the 75 machine is at rest.

77. A welt shoe sewing machine having, in combination, stitch forming devices including a curved hook needle, welt cutting and holding mechanism arranged to be thrown 80 into operation by a pull on the welt when the machine is at rest, and means by which said mechanism may be rendered either operative or inoperative at the will of the operator when the machine is at rest. 85

78. A welt shoe sewing machine having, in combination, stitch forming mechanism including a curved hook needle, welt cutting and holding devices, mechanism for actuating said devices to sever and hold the welt, 90 means operated by a forward pull on the welt for throwing said actuating mechanism into operation comprising a device for gripping the welt between the shoe and the supply upon stopping the machine and 95 thereby rendering said means operative, and means by which the gripping device may be rendered inactive when the machine is at rest.

79. A welt shoe sewing machine having, in 100 combination, stitch forming machinsm including a curved hook needle, means for severing the welt after the completion of a seam, and a welt holder inactive when the welt is severed and thrown into operation 105 after a shoe is placed in the machine for engaging the end of the welt and holding the same in position with relation to the shoe until the welt is attached to the shoe by one or more stitches.

WILLIAM C. MEYER.
